UNITED STATES PATENT OFFICE

2,577,529

CARTON HANDLING MACHINE

Charles E. Kerr, San Jose, Calif., and Roscoe Elsheimer, Hooperston, Ill., assignors to Food Machinery and Chemical Corporation, a corporation of Delaware

Application July 8, 1946, Serial No. 681,980

17 Claims. (Cl. 93—6)

1

The present invention appertains to a method and apparatus for handling cartons used for packaging merchandise such as food products or the like.

More particularly the present invention relates to a method and apparatus for handling and filling cartons having a formed and secured body portion folded and collapsed in flattened condition and a collapsed cover hinged thereon and overlying the same.

One object of the present invention is to provide a method of forming, filling, and closing collapsed cartons while the cartons are in a continuous uninterrupted flow.

Another object is to provide a method of opening and setting up collapsed cartons while the cartons are in a continuous flow.

Another object is to provide a method of opening up the collapsed flanges of the covers of the cartons and folding the covers over the cartons to thereby close the same while the cartons are in a continuous flow.

Another object is to provide a machine for handling collapsible cartons and for forming, filling, and closing the cartons while the same are in a continuous and uninterrupted flow.

Another object is to provide a machine for advancing collapsed one piece cartons in a continuous and uninterrupted flow past a carton opening, filling, closing, and discharge station for turning back the cover of the cartons, for opening and erecting the body of the cartons, for filling the cartons, for erecting the flanges of the cover of the cartons, for closing the cover, and for pressing the filled and closed cartons into shape for subsequent wrapping or labeling thereof.

Another object is to provide a machine for feeding collapsed cartons in a continuous flow from a supply magazine to a place of use and for opening and blocking the cartons during uninterrupted conveyance thereof.

Another object is to provide a machine for conveying collapsed cartons provided with hinged covers overlying their body portions in a continuous flow along a predetermined path and for turning back the covers to expose the body portions of the cartons.

Another object is to provide a machine for erecting the collapsed walls of the body portion of the cartons to open and set up the cartons for subsequent filling thereof.

Another object is to provide a machine for conveying collapsed cartons having hinged covers overlying their body portions in a single file and

2

in spaced relation along a predetermined path, for elevating and turning back the covers to expose the folded and collapsed body portions of the carton and for erecting the walls of the collapsed body portions to open and set up the same for subsequent filling thereof.

Another object is to provide a machine for closing the covers of the cartons after the cartons have been filled with merchandise and while the same are conveyed in a continuous and uninterrupted flow.

Another object is to provide a machine for closing the covers of cartons provided with collapsed flanges on their sides and for opening up and erecting said flanges prior to the closing of the covers.

Another object is to provide a machine for handling collapsed cartons and for opening, filling, and closing the same which is fully automatic, continuous in operation, and of simple and inexpensive construction.

Other and further objects and advantages of the present invention will become apparent from the following description and drawings in which:

25 Fig. 1 is a plan view of the carton handling machine of the present invention.

Fig. 2 is a plan view of the front end of the machine illustrating the carton magazine and the carton opening unit, certain parts being broken away while others are shown in section.

Fig. 22 is an enlarged perspective view of the no carton no fill control mechanism, certain parts being broken away while others are shown in section.

Fig. 23 is an enlarged side elevation of the no carton no fill control mechanism with the cover thereof removed and a portion of the supporting bracket broken away.

Fig. 24 is a section to a portion of the filling unit and the carton opening unit taken along line 24—24 of Fig. 1.

Fig. 24A is a somewhat diagrammatic horizontal section at a reduced scale of the filling unit of the machine; the line along which this section is taken is partially indicated by line 24A—24A in Fig. 24.

Fig. 25 is a section of a portion of the carton filling unit shown in Fig. 1 taken along line 25—25 thereof.

Fig. 26 is a plan view of a portion of the carton feed turret and a portion of the turret of the filling unit illustrating the feeding of the cartons into the filling unit, certain portions of the turret of the filling unit being broken away while others are shown in section.

Fig. 27 is a section of a portion of Fig. 25 taken along line 27—27 thereof.

Fig. 28 is a plan view of the carton closing and the carton discharge unit of the machine, a portion thereof being broken away to reduce the length of the same.

Fig. 29 is a side view of the carton closing and discharge unit illustrated in Fig. 28, certain portions being omitted.

Fig. 30 is a longitudinal section of a portion of Fig. 28 taken along line 30—30 thereof.

Fig. 31 is a transverse section of Fig. 28 taken along line 31—31 thereof.

Fig. 32 is a horizontal section of the front end of the carton closing unit taken along line 32—32 of Fig. 29.

Fig. 33 is a longitudinal section through a portion of Fig. 28 taken along line 33—33 thereof.

Fig. 34 is a horizontal section of a portion of Fig. 29 taken along line 34—34 thereof, certain parts being shown in elevation.

Fig. 35 is a transverse section of Fig. 29 taken along line 35—35 thereof.

Fig. 36 is a perspective view of the universal mounting of one of the turret arms of the carton closing unit of the machine, certain parts being broken away while others are shown in section.

Fig. 37 is a perspective view of the cover closing mechanism of the machine.

Fig. 38 is a horizontal section through the car-

ton discharge unit of the machine taken along line 38—38 of Fig. 30.

Fig. 39 is a transverse section of the carton discharge unit taken along line 39—39 of Fig. 30.

Fig. 40 is a perspective view of the carton prior to closing thereof showing the flanges of the cover in folded and flattened condition and overlying the underside of the cover of the carton.

Fig. 41 is a perspective view of the carton illustrated in Fig. 40 but showing the flanges of the cover of the carton in opened or erected position.

Fig. 42 shows a section of the carton shown in Fig. 41 taken along line 42—42 thereof with the cover disposed in closed position.

Figs. 43 to 46, inclusive, are diagrammatic plan views of a portion of the conveyor mechanism of the closing unit of the machine and the carton turning mechanism associated therewith and illustrating in successive steps the turning of a filled carton thereby.

Figs. 47 to 50, inclusive, are perspective views of portions of the conveyor mechanism, the flap opening turrets, and other parts of the closing unit associated therewith showing in successive steps the advancement of a filled carton past the turrets and the opening of the flaps of the cover of the carton thereby, portions of the carton discharge unit are illustrated in connection with Figs. 49 and 50.

Fig. 51 is a side elevation of a portion of the cover closing unit and a portion of the carton discharge unit showing a carton in different positions of advancement relative thereto and illustrating the manner in which the covers of the carton are closed thereby, certain portions of Fig. 51 have been broken away.

Fig. 52 is a diagram of the entire electric control and power supply circuit of the machine.

In general, the carton handling machine of the present invention (Fig. 1) comprises a magazine A, a carton opening unit B, a carton filling unit C, a carton closing unit D, a carton discharge unit E, and a "no carton-no fill" control mechanism G.

In the operation of the machine the folded and collapsed cartons are placed into the magazine A and are conveyed therefrom by the carton opening unit B to the filling unit C. During the conveyance of the cartons from the magazine A to the filling unit C, the cover of the cartons is turned back and the body portion of the cartons is opened and set up for subsequent filling thereof. The opened cartons are thereupon advanced through the filling unit C, are filled with merchandise, and delivered to the carton closing unit D, which opens and erects the flanges of the cover of the cartons, closes the cover of the cartons, and delivers the closed and filled cartons to the discharge unit E which presses the filled and closed cartons into shape and discharges the same from the machine. The cartons are conveyed in continuous flow through the machine by appropriate conveyor mechanism associated with the various units and the opening, filling, and closing operations are performed during the continuous and uninterrupted travel of the cartons through the machine.

The no carton-no fill mechanism G associated with the machine stops the operation thereof in case the magazine should run empty so that the operation of the filling unit C is not continued when there are no cartons supplied to receive the charges of material therefrom.

With the foregoing description in mind, the

construction and operation of the machine will now be specifically described.

The carton opening unit B of the machine of the present invention comprises a conveyor 1 to which the carton supply magazine A is secured, a cover or lid turning and elevating mechanism 2, and a carton body opening mechanism 3.

The folded and collapsed cartons to be handled by the machine are placed lids uppermost in a vertical stack into the carton supply magazine A from which they are separately fed in a continuous flow and in spaced relation past the lid or cover elevating and turning mechanism 2 and the body opening mechanism 3 by the conveyor 1. During the advancement of the collapsed cartons toward and past the lid turning mechanism 2, the lids or covers of the cartons are elevated and turned back to expose the collapsed body portions of the cartons which are subsequently opened and set up by the carton body opening mechanism 3 so that the cartons leaving the carton body opening mechanism are ready to receive the products or articles to be packed therein as they are subsequently advanced through the filling unit C.

To facilitate a clear understanding of the construction and operation of the present invention a brief description of the collapsed type of carton for which the machine is especially adapted is first given herein.

This carton (Figs. 18, 19, and 20) is manufactured as a completely formed box preferably made from card board or similar material which has been folded, collapsed, and flattened for shipping and handling purposes. In opening the carton to set the same up for filling thereof, such operations as forming the bottom by gluing or tucking-in of locking or closure flaps or tabs are not necessary since the body portion and lid or cover of the carton are completely formed, assembled, and glued so that it is merely a matter of opening and setting up the carton to prepare the same for subsequent filling thereof.

The carton F, Fig. 20, is preferably made from a single blank of stock material which is creased, bent, and glued to form a rectangular box which comprises a body portion 6 and a cover 7 hinged thereon. The body portion 6 includes a rectangular bottom 8, side walls 9 and 10, and end walls 11 and 12, while the cover or lid 7 hinged to the marginal edge of the side wall 9 includes a lid portion 13 provided with end flaps 14 and 15 and a side flap 16 forming a continuous flange 17. The side wall 10 of the carton is provided with tabs 18 and 19 bent at right angles thereto and glued or otherwise firmly secured to the end walls 11 and 12, respectively, while the end walls 11 and 12 are provided with tabs 20 and 21, respectively, bent at right angles thereto and glued or otherwise firmly secured to the side wall 9.

The end flaps 14 and 15 of the cover 7 are provided with tabs 22 and 23, respectively, which are bent at right angles thereto and are glued or otherwise firmly secured to the side flap 16 of the cover 7. A locking tab 24 formed as an integral part of the side wall 10 and projecting outwardly and downwardly from the upper marginal edge thereof is provided to catch behind the straight edges 25 and 26 of the tabs 22 and 23 when the cover is closed with the flange 17, i. e., the flaps 14, 15, and 16 overlying the end walls 11 and 12 and the side wall 10, respectively, of the body portion of the carton so that the cover 7 is firmly held in closed position.

To permit easy shipment and handling of the

cartons and to conserve as much shipping space as possible, the side and end walls of body portion 6 and the continuous flange of the cover 7 of the carton F are collapsed within the confines of the bottom and cover, respectively, i. e., are folded along lines 27 to 31 and collapsed in the manner as clearly illustrated in Fig. 19. The cover 7 is thereupon swung over the body portion in the direction of arrow 32 (Fig. 19) and the entire carton is flattened, as shown in Fig. 18. Preferably the tabs 18 and 19 are only glued to the end walls 11 and 12 at the portion between the fold lines 28 and 29 and the side wall 10 so that the inner corners of the tabs are free to fold down flat, as shown in Fig. 19. In the collapsed and flattened condition the cartons are packed in stacks in shipping boxes in which they are shipped and distributed for use.

Magazine and carton opening unit

Referring now more specifically to the construction of the carton opening unit B and the magazine A associated therewith, it should be noted that the conveyor 1, previously referred to herein (Figs. 2, 3, 4, 5, and 6), comprises a frame structure 40 which includes a pair of U channels 41 and 42 secured to each other by a plurality of transverse braces 43 (Figs. 2, 4, and 5). The U channels 41 and 42 are so disposed with respect to each other as to form a hollow beam structure 46 supported in substantially horizontal position at desired height by means of a supporting column 47 partially shown in Fig. 3 which is secured to the lower flanges 48 and 49 of the channels 41 and 42 by means of a U-shaped supporting bracket 50 (Figs. 3 and 5) adjacent the front end 51 of the beam structure 46. Secured to web portions 52 and 53 of the U channels 41 and 42 by means of flanges 54 and cap screws 55 are bearings 56 and 57 (Figs. 2, 3, and 7) within which a shaft 58 is rotatably mounted and extends transversely of the beam structure 46 through aligned openings 59 and 60 in the web portions 52 and 53 (Fig. 7). Retaining collars 61 and 62 secured by set screws to the shaft 58 are provided to retain the shaft 58 in proper position with respect to the beam structure 46. Fixed to the shaft 58 intermediate the web portions 52 and 53 of the U channels 41 and 42 by means of a set screw is a sprocket 63 (Fig. 7).

Secured to the rear end 65 of the beam structure 46 is an U-shaped bracket 66 by means of which the conveyor 1 is removably secured to the frame structure of the inlet conveyor 67 (Figs. 1 and 21) of the filling unit C in the manner described later on. If it is desired to use the carton opening unit B by itself for opening cartons to be subsequently manually filled and closed, the supporting bracket 66 may be secured to an auxiliary support, not shown, for supporting the rear end of the opening unit B. The supporting bracket 66 is provided with bearings 75 and 76 (Fig. 2) within which a shaft 77 is rotatably received. This shaft extends through aligned openings in the web portions 52 and 53 and is retained against lateral movement within the bearings 75 and 76 by means of a retaining collar 80 and the hub portion 83 of the sprocket 84 secured to the shaft 77 for rotation therewith.

Fixed to the shaft 77 by means of a set screw 85 is a sprocket 86 which is disposed intermediate the bearings 75 and 76. Trained around sprockets 63 and 86 is an endless conveyor chain 87 (Figs. 2 and 4) provided with a plurality of carton pusher members 88 (Fig. 12) of L-shaped

construction. These pusher members 88 are secured to the chain 87 at one side thereof by means of mounting links 89 forming a part of the chain 87. The pusher members are arranged in spaced relation and are disposed at equal distances from each other along the conveyor chain 87. The upper run 87a of the conveyor chain 87 overlies and is supported by a chain guide plate 90 (Figs. 4 and 5) welded to the braces 43 and extending parallel with the beam structure 46 between sprockets 63 and 86.

The hub portion 83 of the sprocket 84, previously referred to herein, is fixed to shaft 77 (Figs. 2 and 3) by means of a key 92 and is provided with a flange 93 having arcuate slots 94 through which cap screws 95 extend which are threadedly secured to the body portion 96 of the sprocket which is rotatable relative to the hub portion 83 but is normally fixed thereto for rotation therewith when the cap screws 95 are tightened to firmly secure the body portion 96 of the sprocket 84 to the flange 93 of the hub 83. The adjustability of the sprocket 84 relative to the flange 93 enables rotative adjustment of the sprocket with respect to the shaft 77 so as to permit adjustment of the drive mechanism of the carton opening unit B for timed operation with the remaining units of the machine.

Secured to the top of the beam structure 46 (Figs. 2 and 5) is a conveyor table 101 which comprises angle members 102 and 103 and a wide table plate 104 provided with a side wall 105. The angle members 102 and 103 and table plate 104 are secured to the upper flanges 48a and 49a of the U channels 41 and 42, respectively, by means of countersunk screws 106. The angle members 103 and the table plate 104 which forms the front end continuation thereof are disposed parallel to the angle member 102 and are spaced therefrom so as to permit travel of the pusher members 88 of the conveyor chain 87 therebetween. These pusher members 88 extend slightly above the surface of the conveyor table formed by the plate 104 and the horizontal leg portions 107 and 108 of the angle members 102 and 103 so as to engage the cartons and to advance the same from the receiving end 109 of the conveyor to the rear end 110 thereof in the manner as will be more specifically explained later on.

The table plate 104 provides in conjunction with the leg portion 107 of the angle 102 a wide table surface 101a at the receiving end of the conveyor 1 for the reception of the collapsed cartons and this table surface gradually narrows to a table surface 101b of smaller width between the upright legs 111 and 112 of the angle members 102 and 103. The legs 111 and 112 of the angle members 102 and 103, respectively, and the side wall 105 of the plate 104 are disposed in a vertical position and form guide walls for retaining the cartons in proper position of the table 101 during their conveyance along the same. The guide wall 105 is bent, as shown at 113, and is joined with the guide wall 112 to form a continuous guide wall therewith.

Disposed above and secured to the receiving end 109 of the conveyor 1 above the table 101 is the carton supply magazine A (Figs. 2, 3, 4, and 7) which comprises a vertically extending cage structure 114 of rectangular configuration in cross section slightly larger than the size of a collapsed carton. This cage structure includes a plurality of vertically disposed spaced guides 115 secured at their lower ends to a rectangular frame 116 supported upon the guide walls 111

and 105 of the conveyor table 101. The frame 116 is provided with straps 117 and 117a rigidly secured thereto in any convenient manner. The free end of the strap 117 (Fig. 3) is secured by means of cap screws 118 to a supporting bracket 119 firmly attached to the web portion 53 of the U channel 42 while the free end of the strap 117a is secured by cap screws 118a (only one of which is shown in Fig. 2) to the web portion 52 of the U channel 41 so that the entire magazine A is firmly held in fixed position above the receiving end 109 of the conveyor 1 and in spaced relation to the surface of the conveyor table 101.

The magazine A may be of any desired height and is preferably provided at its upper end with a rectangular frame (not shown) which is similar to the frame 116, to which the upper ends of the guides 115 are attached so as to hold the same in proper position.

Disposed below the magazine A and secured to the surface of the conveyor table 101a by countersunk screws 120 (Fig. 2) are spacing plates 121 and 122 arranged in spaced relation with respect to each other to provide passage of the pusher members 88 of the conveyor chain 87 therebetween. These plates form the bottom of the magazine and support the stack of collapsed cartons therein and their thickness is such that only the lowermost collapsed carton in the magazine 30 A is engaged and shifted from the magazine by the pusher members 88 upon operation of the chain 87 so that the cartons are separately discharged from the magazine and are advanced in spaced relation along the conveyor table 101.

Secured to the rear portion 123 of the magazine frame 116 (Figs. 2, 3, 4, and 7) is a control gate structure 124 which comprises a gate 125 secured to a bracket 126 fastened to the frame portion 123 by means of cap screws 127. The bracket 126 is provided with a vertically disposed elongated opening 128 and extending through the same is a cap screw 129 threadedly secured to the gate 125. When the cap screw is tightened, the gate 125 is firmly held in any desired position 45 of adjustment on the bracket 126. The position of the gate 125 with respect to the spacing plates 121 and 122 is adjusted by loosening the cap screw 129 and by shifting the same up or down within the slot 128 whereby the elevation of the gate 50 125 is accordingly varied so as to increase or decrease the size of the discharge opening 130 formed between the lower edge of the gate 125 and the spacing plates 121 and 122. The desired adjustment of the guide plate 125 is thereupon 55 maintained by tightening the cap screw 129 whereby the gate is firmly locked in position. The arrangement of the magazine A with respect to the lid turning mechanism 2 and the body opening mechanism 3 is such that the cartons 60 may be stacked in their collapsed form, as shown in Fig. 18, in the magazine with their lids uppermost and the outer front edges 13a of the lids extending parallel with and adjacent to the side 116a of the magazine which extends immediately 65 above and parallel with the guide wall 105 of the conveyor table 101.

Secured to the rear portion 123 of the magazine frame 116 by means of a cap screw 131 and a clamping plate 132 (Figs. 2 and 4) is a leaf 70 spring 133 which extends downwardly from the frame 116 toward the conveyor table 101 and is bent at substantially right angles so that its lower portion 134 is disposed substantially parallel to the conveyor table and in closely spaced relation 75 therewith. The spacing of the lower portion 134

of the leaf spring 133 with respect to the conveyor table is such that the free end of the spring will overlie and exert a slight pressure upon the side wall 9 of the collapsed carton as the latter is discharged from the magazine A and advanced along the conveyor table 101. The function of this spring is to hold the body portion of the carton in collapsed condition during its discharge from the magazine and a part of the lid turning operation as will be more specifically described later herein.

Secured to the guide wall 112 adjacent the angularly disposed guide wall portion 113 is a carton hold down guide 136 (Figs. 2, 4, and 5) while a similar hold down guide 137 is attached to the guide wall 111. Both hold down guides are disposed above the conveyor table in such spaced relation relative thereto that they will overlie and engage the upper surface of the side walls 10 and 9 of the collapsed cartons so as to hold the body of the cartons in collapsed condition on the conveyor table 101 during the lid turning operation. The front ends of the hold down guides 136 and 137 are tapered, as shown at 136a and 137a (Figs. 2 and 4) so as to facilitate the introduction of the collapsed carton body between the guides and the conveyor table 101.

Secured to the guide wall 112 and the guide wall portion 113 of the conveyor table 101 intermediate the magazine A and the carton body opening mechanism 3 by means of supporting brackets 138 and 139 (Figs. 2, 3, and 5) is the cover or lid elevating and turning mechanism 2 which comprises a turning or guide rod 140 secured at its front end 141 by welding to the conveyor table 101. The front portion 143 of the rod 140 (Figs. 2 and 5) is gradually upwardly inclined and extends diagonally of the conveyor table. The rear portion 145 of the rod 140 is curved downwardly (Figs. 2 and 3) toward 40 and transversely of the table 101 and terminates in a substantially horizontally disposed portion 146 extending parallel to the guide wall 111 and in spaced relation above and exterior of the same.

The body opening mechanism 3, previously referred to, comprises a carton body opening finger 156 and a carton body opening finger 157 (Figs. 2, 4, and 6). The finger 156 is disposed in front of the finger 157 and both are centrally arranged between the guide walls 111 and 112 above the conveyor 1. The finger 156 (Fig. 8) comprises an arm 158 provided with a carton engaging hook 156a for engaging the end wall 11 of the cartons and a hub portion 159 rotatably mounted upon a finger supporting rod 160 fixed within a socket portion 161 of a bracket structure 162 secured to the web 53 of the U channel 42, previously referred to, by means of screws 163 (Fig. 5) and held in spaced relation to the web 53 by bosses 164. The carton body opening finger 156 is further provided with a lateral extension 165 on the free end of which a roller 166 is rotatably mounted. This roller is adapted to engage the cam surface 167 of a rotary cam 168 (Figs. 2, 8, and 10) fixed to a shaft 169 by means of a set screw 170. The shaft 169 is rotatably mounted within a bearing 171 forming a part of the bracket structure 162.

Disposed adjacent the hub portion 159 of the arm 158 is a torsion spring 173, one end of which is secured to a collar 174 fixed to the rod 160 while the other end thereof is secured to the arm 158 by introducing the same into an opening 175 therein. The collar 174 is preferably secured to

the rod 160 by means of a set screw 176 while a plurality of openings 177 are provided in the collar to permit rotative adjustment of the same by means of a wrench after the set screw 176 has been loosened so that the tension of the spring 173 may be varied as described. While the employment of spring 173 may be desirable, the same is not necessary and may be omitted. In such case, the collar 174 is placed directly adjacent the hub portion 159 and merely functions as a retaining collar for the finger 156.

The carton body opening finger 157 (Figs. 2, 4, 6, and 9) comprises an arm 178 provided with a hook portion 179 at its free end for engaging the end wall 12 of the cartons in the manner later described herein. This finger is further provided with a hub portion 180 fixed by means of a set screw 181 to a finger actuating shaft 182 rotatably mounted within a bearing 183 of the bracket structure 162, previously mentioned.

Fixed to the shaft 169 adjacent the bearing 171 by means of a set screw 186 is a sprocket 187, while fixed to the shaft 182 adjacent the bearing 183 by means of a set screw 188 is a sprocket 189. Trained around the sprockets 187 and 189 and a drive sprocket 190 fixed to a shaft 191 (Figs. 2, 3, and 5) rotatably mounted in the bearing portion 192 of the bracket structure 162 is an endless drive chain 193. The shaft 191 is further provided with a sprocket 194 (Figs. 5 and 11) which is fixed thereto for rotation therewith and around which the conveyor chain 87 (Fig. 4) is trained so that upon operation of the conveyor chain 87 the shaft 191 and the sprocket 190 are driven in the direction of arrow 195 (Figs. 3 and 4) and effect operation of the chain 193 and simultaneous rotation of the sprocket wheels 187 and 189 therewith.

Adjustably secured to an ear 198 (Figs. 3, 5, and 11) extending from and forming an integral part of the bearing portion 192 is a link 199 provided with an idler sprocket 200 rotatably mounted thereon by means of a pivot pin 201. The link 199 is provided with a slot 202 through which a cap screw 203 threadedly secured to the ear 198 extends while disposed intermediate the head of the cap screw 203 and the link 199 is a washer 204 so that when the cap screw is tightened the link 199 and the idler sprocket 200 are firmly held in position. This slot and cap screw arrangement, however, permits adjustment of the sprocket 200 relative to the conveyor chain 87 for taking up any slack in the conveyor chain 87. The bracket structure 162 (Figs. 2, 5, 6, and 11) is further provided with an ear 206 provided with an elongated slot 207 within which a pivot pin 208 is adjustably mounted by means of a washer 209 and a nut 210 threadedly secured to one end of the pivot pin. The other end of the pivot pin is provided with a head 211 and rotatably disposed upon the pivot pin 208 intermediate the head 211 and the ear 206 is an idler sprocket 212 which intermeshes with the drive chain 193 and is adapted to be adjusted relative thereto in such a manner as to take up the slack of the chain in the manner as will be obvious to those skilled in the art.

Disposed above and parallel to the conveyor table 101 below the shaft 182 (Figs. 2 and 5) is a cover or hold down plate 215 having a cut out portion 216 of sufficient length to permit movement of the carton body opening fingers 156 and 157 therethrough. The hold down plate 215 is supported by a vertically disposed portion 217 thereof secured by screws 218 to the web 53 of

channel 42 in such a manner that the plate is held spaced a sufficient distance from the conveyor table 101 to permit free movement of the opened and erected carton body between the conveyor table and the plate 215. However, the plate 215 is sufficiently close to the conveyor table 101 so as to retain the carton body in proper position on the conveyor table 101 and to prevent any tilting of the carton body during the opening operations performed upon the same by the fingers 156 and 157.

A cover or lid supporting rod 219 secured by brackets 220 to the guide wall 111 is provided to support the lids of the cartons after they have been turned back and the body portions of the cartons have been opened.

Trained around the sprocket 84 and a sprocket 225 keyed to a drive shaft 226 (Figs. 1 and 24) of the filling unit C is an endless sprocket chain 227, while keyed to the shaft 226 adjacent the sprocket 225 is a sprocket 228. This sprocket 228 is driven by an electric motor 229 by means of an endless drive chain 230 trained around the same and a drive sprocket 231 forming a part of a variable speed change mechanism 232 of well known construction associated with the motor 229.

Operation of carton opening unit

From the above description of the carton opening unit B it will be apparent that upon operation of the motor 229 the conveyor shaft 77 is driven thereby so that the conveyor chain 87 is continuously operated and travels in the direction of arrow 235 (Figs. 2, 3, and 4). The conveyor chain 87 in turn drives the sprocket 194, shaft 191, and sprocket 190 in the direction of arrow 195 (Fig. 3) effecting travel of the chain 193 in the direction of arrow 236 (Figs. 2, 3, and 6) and rotation of sprocket 189, shaft 182, and finger 159 in the direction of arrow 237 (Figs. 3, 4, and 6) while, at the same time, sprocket 187, shaft 169, and cam 168 are driven in the direction of arrow 238 (Figs. 3 and 6). Consequently, the finger 157 is continuously rotated in the direction of arrow 237 in timed relation with the operation of the conveyor chain 87 and the pusher members 88 carried thereby while the finger 156 is raised and released in timed relation therewith by means of the roller 166 and cam 168.

The collapsed cartons F to be handled are stacked body portion down in a vertical column in the magazine A with the edge 13a (Fig. 18) of the lid extending parallel and adjacent the side 116a (Fig. 2) of the magazine so that the bottom of the lowermost carton of the column rests upon the spacing plates 121 and 122. These plates support the stack of cartons in such a manner that always only the lowermost carton is engaged by one of the pusher members 88 traveling through the bottom of the magazine and is shifted thereby from the magazine through the discharge opening 130 (Figs. 4 and 7) thereof below the gate 125 which functions to retain the remaining cartons in the magazine. The cartons are, therefore, removed one after the other by the pusher members 88 and are advanced thereby in spaced relation in a single file and in a continuous uninterrupted flow along the conveyor table 101.

As each carton is discharged from the magazine A and deposited onto the conveyor table 101, it is introduced beneath the leaf spring portion 134 which engages the collapsed carton body at the side wall 9 thereof and guides the same underneath the hold down guide 137. As soon as

5
10

a collapsed carton has been entirely discharged from the magazine A, the cover 7 of the carton springs slightly open due to the resiliency of the material from which the cartons are made, but the body portion of the carton is prevented from doing so since it is held down in completely collapsed condition by the hold down guide 137 and leaf spring 133 bearing with slight pressure upon the side wall 9.

While each carton is advanced with its cover slightly sprung open along the conveyor table 101 in the direction of arrow 240 (Figs. 1, 2, and 4) and past the lid elevating and turning mechanism 2 (Fig. 4), the cover 7 of the carton engages the rod 140 and is first elevated, i. e., cammed upwardly thereby in the direction of arrow 241 from its full line position 242 to its dotted line position 243 (Fig. 5) and is finally turned back about its crease 244 to substantially horizontal position, as shown in dot-dash lines at 245 (Fig. 5), whereby the collapsed body portion is fully exposed.

As pointed out in the above during the first part of the cover turning operation, the leaf spring 133 and hold down guide 137 engage the side wall 9 of the carton and prevent partial opening of the carton body. It should be further noted, however, that the hold down action of the leaf spring 133 and guide 137 retains the body portion of the carton in position on the conveyor table 101 and prevents tilting of the carton relative thereto. Furthermore, as soon as the cover turning operation commences, the side wall 10 of the carton (Fig. 2) is introduced below the hold down guide 136 so that during the entire cover turning operation the body portion of the carton is held in collapsed and flattened condition on the conveyor table 101 so that any tilting of the carton body or opening thereof during the entire cover elevating and turning operation is prevented, especially after the carton has disengaged from the leaf spring 133.

With the cover disposed in substantially horizontal position, as shown at 245 in Fig. 5, and held in this position by the horizontal portion 146 of the rod 140 the carton is now advanced past the carton body opening or blocking mechanism 3, i. e., fingers 156 and 157. As the leading end of the carton approaches and passes beneath the finger 156, the latter is held in its uppermost position, as shown in dotted lines in Fig. 13, by the high portion 167a of the rotary cam 168 which engages the roller 166 so that the hook portion 156a of the finger is held out of engagement with the carton F. While the finger 156 is held in its uppermost position the finger 157 begins to travel through the upper arc of its rotative movement, from the position shown in dotted lines in Fig. 13 to the full line position illustrated in said figure. It will, therefore, be seen that during further advancement of the carton along the conveyor table 101, the body portion of the carton is carried underneath the fingers 156 and 157 and the hold down plate 215 and, as soon as the collapsed end wall 12 at the leading end of the carton has passed beyond the hook portion 156a of the finger 156, the declivity of 167b of the cam 168 travels past the roller 166 whereby the finger 156 is released by the cam 168 and drops either by gravity (if no spring 173 is employed) or under the action of the spring 173 into the space between the collapsed end walls 12 and 11, as shown in full lines in Fig. 13. However, the hook portion 156a does not touch the bottom 8 of the carton, but is

70
75
80
85
90
95
100

held slightly spaced therefrom by the roller 166 engaging the declivity 167b.

When the finger 156 is in its full line position, as shown in Fig. 13, the finger 157 is in the full line position (Fig. 13) well above the collapsed body portion of the carton. As the carton now continues its advancement along the conveyor table 101, the hook portion 156a of the finger 156 hooks behind the collapsed end wall 11 of the carton (Fig. 13) and gradually pulls the same upward into upright or erected position in the manner diagrammatically illustrated in sequence in Figs. 14, 15, and 16 while tilting of the carton body during this body opening operation is prevented by the hold down plate 215. Upon engagement of the hook portion 156a of finger 156 with the end wall 11, the carton body has passed the hold down guide 137 and the trailing end of the carton body emerges from below the hold down guide 136, the rear inner end of which is curved upwardly, as shown at 246 (Fig. 4), so that the same does not interfere with the raising of the end wall 11.

When the carton arrives in the position shown in Fig. 14, the opening finger 157 has entered the body portion of the carton behind the leading end wall 12 and begins to raise the same. However, some raising of the end wall 12 prior to the engagement of the finger 157 therewith is effected by the raising of the end wall 11 by finger 156 and the simultaneous raising of the side walls 9 and 10 therewith.

As soon as the carton has reached the position shown in Fig. 15, the finger 157 has raised the end wall 12 to a substantial extent and when the carton arrives in the position diagrammatically illustrated in Fig. 16 the finger 157 has fully erected the end wall 12 while the end wall 11 at the trailing end of the carton has also been fully erected by the finger 156 in the manner previously described herein. It should also be noted that since the side walls 9 and 10 are folded over the end walls 11 and 12 when a carton is in collapsed condition (Fig. 19), the side walls 9 and 10 are automatically raised and set-up during the raising of the end walls 11 and 12.

During further advancement of the carton, the finger 157 (Fig. 17) swings out of engagement with the leading end wall 12 while the finger 156 pulls the end wall 11 slightly backward and slides out of engagement with the same. At this moment the acclivity 167a of cam 168 engages the roller 166 whereby the finger 156 is returned to its uppermost position.

The carton body is now fully opened and completely free of both fingers 156 and 157 and the carton is carried in opened position along the conveyor 1 with the open cover thereof supported by the cover supporting rod 219 and is now ready for introduction into the filling unit C of the machine and for subsequent filling thereof.

It should further be noted that from the time the finger 156 is released by the cam 168 and drops into the space between the end walls 11 and 12 of the carton body 6 (Fig. 13) until it leaves the carton body (Fig. 17) the finger 156 is free to move upwardly under the urge of the forwardly moving end wall 11 so that while this end wall is raised due to the engagement of the hook portion 156a therewith, the finger 156 is free to follow the upward movement of the end wall 11. However, as soon as the finger 156 has reached its uppermost position, as shown in Fig. 16, the acclivity 167a of the cam 168, which follows up the upward movement of the roller 166, engages

the roller 166 (Figs. 6 and 8), and holds the finger 156 in its uppermost position until the next carton has been advanced therebeneath by the next pusher member 88 whereupon the finger 156 is again released in timed relation with the advancement of this next carton and is dropped into the space between the collapsed end walls 11 and 12 thereof and the operation of the fingers 156 and 157 in regard to the succeeding carton repeats in the same manner as described herein.

In this way, the collapsed cartons are continuously advanced from the magazine A past the cover elevating and turning mechanism or station 2 and the carton body opening mechanism or station 3 in a continuous and uninterrupted flow and in properly timed relation with the operation of the fingers 156 and 157 so that as the cartons emerge from the hold down plate 215 they are fully opened or blocked and ready for filling. To maintain the continuous operation of the carton opening unit it is, therefore, only necessary for the operator to maintain a sufficient supply of collapsed cartons within the magazine A. However, if the machine should run empty no interference between the opening fingers 156 and 157 and the pusher members 88 of the chain 87 will result since the cam 168 will, in such case, elevate the finger 156 and prevent contact thereof with the pusher members 88 and the finger 157 is rotated in such timed relation with respect to the pusher members 88 of the conveyor chain 87 that it will never touch the same.

While the carton opening unit B has been shown connected to the filling unit C, it may be readily detached from the same and used separately for opening up the cartons which thereupon may be manually filled and closed if desired.

Filling unit

The filling unit C of the present invention comprises a carton inlet conveyor 67, a carton filling machine 252, and a carton discharge conveyor 253.

The carton filling machine comprises a frame structure 255 (Fig. 24) to which one end of the frame structure 256 of the carton inlet conveyor 67 is connected by means of bolts 257 while the other end 258 of the frame 256 is secured to the U-shaped bracket 66 of the carton opening unit B by means of bolts 259.

The frame structure 256 includes a lower frame portion 256a and an upper frame portion 256b. The lower frame portion 256a is provided with a gear casing 260 having a vertically disposed sleeve bearing 261 and horizontally disposed bearings 262 and 263 while the upper frame portion 256b includes a gear casing cover 264, a vertically disposed bearing 265, and radially extending arms 266 and 267 to which an arcuate conveyor track 268 provided with a vertically disposed guide wall 269 is secured in any convenient manner. The conveyor 268 and guide wall 269 are so arranged as to form a continuation of the conveyor 1 and guide wall 112 of the carton opening unit B, previously referred to. The gear casing 260 and the gear casing cover 264 are secured to each other by means of flanges 271, 272, and cap screws 273 in a well known manner.

Rotatably mounted within the bearings 262 and 263 of the gear casing 260 and a bearing 274 secured to the frame structure 255 of the filling machine by means of bolts 275 is the drive shaft 226, previously mentioned, which is provided with a worm 276 disposed within the gear casing 260 which meshes with a worm gear 278 keyed to a

shaft 279 rotatably mounted within the bearings 261 and 265. The shaft 279 is provided at its upper end with a carton feeding or inlet turret 281 while fixed to the lower end of the shaft 279 by means of a set screw 282 is a sprocket wheel 283. The carton feed turret 281 is rotatably disposed on the shaft 279 but is connected with the shaft 279 for rotation therewith by means of a collar 285 (Fig. 21) keyed to the shaft 279 and provided with radially extending bosses 286 and 287 within which set screws 288 and 289 are threaded in such a manner that the free end of the set screws engage an upstanding portion 290 of the hub of the turret 281 so that by turning the set screws 288 and 289 rotative adjustment of the feed turret 281 relative to the conveyor 1 of the carton opening unit B is obtained for permitting accurate timing of the turret 281 relative to the conveyor 1. The body portion of the feed turret 281 comprises a circular disc 292 provided with radially extending arms 293 spaced a predetermined distance relative to each other around the periphery of the disc so as to receive the cartons therebetween and to transfer them from the conveyor 1 of the carton opening unit B to the filling machine 252 along the arcuate track 268.

Disposed within a gear casing 301 forming a part of the frame structure 255 of the filling machine is a worm gear 302 provided with a long hub portion 303 rotatably mounted within a vertically disposed bearing 304 forming an integral part of the casing 301. The drive shaft 226, previously referred to, extends into the gear casing 301 and is rotatably disposed within bearings 306 of the gear casing 301, only one of which has been shown in Fig. 24. Keyed to the shaft 226 and disposed within the gear casing 301 in intermeshing relation with respect to the worm gear 302 is a worm 307. Upon rotation of the shaft 226, in the direction as indicated by arrow 308 in Fig. 24, the worm gear 302 is rotated in a counterclockwise direction.

The hub portion 303 of the worm gear 302 is internally threaded, as shown at 310, and threadedly received therein is an externally threaded vertical sleeve shaft 311 having a hand wheel 312 fixed to its lower end for rotation therewith. A set screw 313 threadedly secured to the hub portion 303 is provided to lock the tubular shaft 311 against rotation with respect to the hub portion 303 of the worm gear 302.

Mounted upon the upper end of the tubular shaft 311 by means of a vertically disposed hub portion 315 is a horizontally disposed turret 316 held in predetermined vertical position with respect to the tubular shaft 311 by means of a bearing collar 317 fixed to the tubular shaft 311 by a set screw 318. The turret 316 is provided with a plurality of bosses 320 within each one of which a plunger rod 321 is fixed. The worm gear 302 is provided with a plurality of upstanding bosses 322 within which the lower ends of the plunger rods 321 are slidably received and whereby a driving connection between the worm gear 302 and the turret 316 is established, while, at the same time, vertical adjustment of the turret relative to the worm gear is permitted upon rotation of the hand wheel 312 after the set screw 313 has been loosened for purposes as will be explained later on.

Rotatably mounted within the tubular shaft 311 is a shaft 325 provided at its lower end with a hand wheel 326 fixed thereto by means of a set screw 327. The upper end of the shaft 325 projects above the turret 316 and carries a

70

sprocket 329 fixed thereto. Trained around the sprocket 329 and sprockets 330 (Fig. 24A) of a plurality internally threaded sleeves 331 (only two of which are shown in Fig. 24) is an endless sprocket chain 332. Each of the internally threaded sleeves 331 is rotatably mounted within a bearing boss 335 forming an integral part of the turret 316. A retaining collar 336 secured to the lower end of each sleeve 331 by means of a set screw 337 maintains the sleeves in their proper positions on the turret 316. Threadedly mounted within each sleeve 331 is a supporting rod 338, the upper end of which is secured to an annular supporting flange 339 of a revolving table structure 340.

This table structure comprises a table 342 provided at its periphery with a series of filling openings 343 disposed in spaced relation with respect to each other, and an upstanding annular flange 344. Secured to the table 342 in registration with the openings 343 by means of an annular ring 346 are the upper tubular sections 347 of volumetric measuring cups 348, the lower tubular sections 349 of which are telescoped over the upper sections thereof, as shown in Fig. 24. The lower sections of the cups are secured by means of screws 351 and 352 to an annular supporting ring 353. Attached to the annular supporting ring 353 by means of the screws 351 in registration with each filling opening 353 and the volumetric measuring pocket 348 associated therewith is a discharge funnel 354 of rectangular configuration (Figs. 24, 25, and 27) provided with downwardly sloping inner walls to effect the discharge of materials from the volumetric measuring pockets into the cartons when the same are disposed therebeneath. The lower end of each funnel 354 is provided with a horizontally disposed rectangular flange 355 which is slightly larger than the mouth of the carton so as to overlie the same in closely spaced relation when the cartons are disposed in receiving position below the funnels 354.

The annular supporting ring 353 is firmly attached to an upstanding flange 357 of the turret 316 by means of bolts 358 while the annular supporting flange 339 is rigidly secured to the annular ring 346 and table 342 by means of countersunk screws 359 so that upon rotation of the turret 316 the table 342, the volumetric measuring pockets 348, and the funnels 354 are rotated as a unit therewith. Secured to the periphery 360 of the turret 316 by means of set screws 361 is a carton feed ring 362 (Figs. 24 to 27) provided with a plurality of radially extending spaced fingers 363 for receiving the cartons therebetween and for advancing the cartons through the filling machine upon rotation of the turret 316.

Disposed adjacent the feed ring below the fingers 363 is an arcuate conveyor table 364 (Figs. 1, 24, 24a, and 25 to 27) extending from the rear end 365 of the arcuate conveyor table 368 of the inlet conveyor 67 to the front end 366 of an arcuate conveyor table 367 of the outlet conveyor 253 which is of the same construction as the table 268 so that a continuous conveyor table surface from the inlet conveyor 67 through the filling machine 252 to the outlet conveyor 253 is formed.

Secured to the frame structure 255 of the filling machine adjacent the arcuate conveyor table 364 by means of a plurality of studs 370 is an arcuate guide rail 371 extending from the vicinity of the feed conveyor 67 to the discharge con-

veyor 253. This rail is adapted to maintain the cartons in position during their travel through the filling machine.

Mounted above the conveyor table 342 by means of a supporting column 373 secured by a bracket 374 to the frame structure 255 of the machine is a stationary supply hopper 375 within which an agitating worm 376 is rotatably mounted by means of a shaft 377. The shaft 377 and worm 376 are driven by the shaft 226 in any convenient manner through sprocket gears and chains, not shown.

Secured to the column 373 by means of a collar 379 is a bracket 380 to which an arcuate valve plate 381 is secured. This valve plate is horizontally disposed and projects into a slot 382 formed between the annular supporting ring 353 and the funnels 354. The valve plate 381 is disposed directly below the volumetric measuring cups 348 in the region of the discharge opening 383 of the hopper in such a manner that materials discharged from the hopper into the measuring cups cannot drop into the funnels 354 and cartons therebelow until each cup has moved beyond the stationary valve plate 381 and out of registration with the discharge opening 383 of the hopper 375.

Disposed above and exterior of the conveyor table of the inlet conveyor 67, the filling machine 252, and the discharge conveyor 253 is a carton cover supporting rod 385 which forms the continuation of the supporting rod 219 of the opening unit. This rod is adapted to support the cover of the carton as the same travels through the filling machine. The rod 385 is supported by appropriate brackets at various locations around the filling machine, as will be obvious to those skilled in the art. A certain portion of the carton rod 385 is flattened, as shown at 386, and is secured by means of a set screw 387 to a supporting collar 388 attached to the column 373 (Fig. 25).

Secured to the conveyor table 364 adjacent the supply hopper 375 is a bracket 390 to which the actuating rod 391 of an eccentric 392 is attached by means of washers 393, nut 394, and rubber cushions 395 and 396. The eccentric 392 is mounted upon the shaft 397 of an auxiliary motor 398 so that upon operation of this motor a rapid vibration of the conveyor table 364 in the region below and behind the supply hopper 375 is obtained to facilitate the distribution of the material in the cartons during the filling operation.

Secured to the hopper 375 and overlying the table 342 in closely spaced relation are guide walls 399 and 400 spaced from each other to form a guide channel 401 therebetween. The guide wall portion 402 of guide wall 399 forms a strike off member which removes excess material from the measuring pockets as they travel past the same and guides the material in the direction of arrow 403 (Fig. 1) back to the empty pockets prior to their registration with the hopper 375, as shown at 404 in Fig. 1, so that the excess material falls into the pockets and is utilized for filling the same.

The outlet conveyor 253 of the filling machine is of the same construction as the inlet conveyor 67, previously referred to herein, with the exception that the worm gear 278 is omitted and shaft 279a is driven directly from the inlet conveyor by means of a chain 406 (Fig. 1) trained around the sprocket wheel 283 on shaft 279 and the sprocket wheel 283a fixed to the shaft 279a so that the turrets 281 and 281a are driven in the

same direction, as indicated by arrows 407 and 408 in Fig. 1.

Operation of carton filling unit

During the operation of the machine, the carton inlet and outlet turrets 281 and 281a are driven in the direction of arrows 407 and 408 (Fig. 1), respectively, the revolving table 342 and measuring pockets 348 are rotated in the direction of arrow 409 and the feed screw 376 is rotated in the direction of arrow 410 while the portion of the conveyor table 364 below and behind the supply hopper 375 is vibrated by the motor 389.

The cartons presented to the feed turret 281 by the conveyor 1 of the carton opening unit B are advanced along the arcuate conveyor table 268 by the fingers 293 and are presented to the feed ring 362, the fingers 363 of which advance the cartons in spaced relation in a continuous flow through the filling machine 252 and subsequently introduce the same between the fingers 293a of the discharge turret 281a which convey the cartons along the arcuate conveyor table 367 and discharge the same from the filling machine onto the conveyor of the carton closing unit D, referred to herein later on.

While the cartons are advanced through the filling machine in this manner, the volumetric measuring pockets 348, one of which is in registration with each carton traveling through the machine, are filled as they travel into registration with the discharge opening 383 of the hopper 375. However, discharge of the material received within these pockets is prevented by the valve plate 381 until the pockets have been moved out of registration with the discharge opening 383 of the hopper 375. As the filling pockets move out of registration with the hopper discharge opening, surplus material is removed therefrom and returned by the guide channel 401 to the incoming empty measuring pockets at point 404 (Fig. 1). Thereupon the measuring pockets travel past the rear end of the arcuate valve plate 381 and the material within the pockets 348 is

now discharged through funnels 354 into the cartons F positioned therebeneath. The discharge of the material into the cartons and the leveling out of the same therein is assisted by the rapid vibration of the portion of the conveyor table 364 directly behind the supply hopper 375 which is effected by the motor 398, previously referred to. Any falling of the material from the cartons is prevented by the horizontally disposed flange 355 of the funnels 354. The filled cartons continue their travel with their covers resting on the supporting rod 385 and are finally presented to the discharge turret 281a, the fingers 293a of which advance the cartons along the arcuate table portion 367 and present the same endwise to the conveyor of the carton closing unit D.

The amount of the material discharged into the cartons is determined by the size of the measuring pockets 348 which may be varied by releasing the lock screw 326a and turning the hand wheel 326 in one or the other directions whereby the supporting rods 338 are rotated by means of the sprockets 329, 330, and endless chain 332 and are screwed up or down relative to the sleeves 331 depending upon the direction of rotation of the hand wheel 326. This up or downward movement of the supporting rods 338 effects a corresponding movement of the table 342 and the upper sections 347 of the volumetric measuring pockets 348 so that they are either telescoped 75 away from or toward the lower sections 349

whereby the volume of the pockets may be increased or reduced as desired. After the desired adjustment of the volumetric measuring pockets 348 has been effected, the lock screw 326a is again tightened.

Cartons of different height may be handled by the filling machine. To adjust the machine for cartons of different height it is only necessary to release the lock screws 313 and 326a and to turn the hand wheel 312 in one or the other direction while hand wheel 326 is held against rotation, whereby the turret 316 table 342, measuring pockets 348, and funnels 354 may be raised and lowered, as desired, so as to accommodate the cartons and to position the funnels 354 in close proximity to the mount of the cartons to be handled by the machine. After the desired adjustment has been made, the lock screws 313 and 326a are again tightened.

Carton closing and discharge units

The carton closing mechanism D (Figs. 1, 28, 29, and 30) comprises a conveyor mechanism 425, a carton turning mechanism 426, a flap opening mechanism 427, and a cover or lid closing mechanism 428. After the cartons have been opened by the carton opening unit B and have been filled with a measured quantity of material by the filling unit C, as described in the above, the cover 7 thereof is in a position, as shown in Fig. 40, and the continuous flange 17 of the cover, i. e., the end flaps 14 and 15, as well as the side flap 16, are still in their collapsed position and overlie the under side of the lid portion 13, in the manner as shown in Fig. 40.

To close the cover of the cartons it is, therefore, necessary to open up and erect the end flaps 14 and 15 and the side flap 16 (Fig. 41) and to close the cover 7 (Fig. 42) with the continuous flange 17 overlying the walls 10, 11, and 12 of the body portion 6 of the cartons and the edges 25 and 26 of the tabs 22 and 23 in locking engagement with the locking tab 24 of the side wall 10 so that the cover is locked in closed position to the body portion 6 whereby accidental opening of the cartons and spilling of the contents thereof during further handling of the cartons, such as wrapping or labeling thereof, is prevented.

In the operation of the closing unit D of the machine the filled cartons having their covers in open position are received endwise by the conveyor mechanism 425 from the arcuate table 367 of the outlet turret 253 of the filling unit C and are advanced by the conveyor mechanism 425 past the carton turning mechanism 426 which turns the cartons with their covers 7 into leading position and advances them in this position sidewise past the flap opening mechanism 427 where the continuous flange 17 of the cover, i. e., the end flaps 14 and 15, and the side flap 16 are opened and erected from the position shown in Fig. 40 to the position as illustrated in Fig. 41. Thereupon during further advancement of the filled cartons by the conveyor mechanism 425 past the cover closing mechanism 428, the covers 7 of the cartons are swung to substantially closed position with the continuous flange 17 thereof overlying the walls 10, 11, and 12 of the body portion 6 of the cartons.

After the covers of the cartons have been substantially closed, the cartons are presented to the carton discharge and presser unit E which comprises a discharge conveyor 429 and a plurality of presser rolls 430. The discharge conveyor 429 advances the cartons past the presser rolls 430

which force the covers into finally closed position with the edges 25 and 26 of tabs 22 and 23 into locking engagement with the locking tab 24, and press the cartons into correct rectangular shape.

Thereupon the closed cartons are discharged by the conveyor 429 from the machine preferably directly into a wrapping and labeling machine where the cartons are wrapped and labeled. Finally the wrapped and labeled cartons are packed into shipping boxes in the manner well known in the art.

Referring now specifically to the construction of the carton closing unit D and discharge unit E, it will be noted that the conveyor mechanism 425 (Figs. 28 to 35) comprises a frame structure 433 formed by a plurality of U channels 434, 435, 436, and 437. The U channels 434 and 435 (Figs. 29, 31 to 34, inclusive) are disposed in horizontal position at the front end of the carton closing unit

D and are secured in parallel and spaced relation with respect to each other by means of transverse braces 438 (Fig. 33) while the U channels 436 and 437 are horizontally disposed intermediate the U channels 434 and 435 and the discharge and presser unit E and are secured to each other in parallel and spaced relation by means of a plurality of transverse braces 439 (Figs. 30 and 35). Secured to the front ends 440 of the U channels 434 and 435 (Figs. 28, 31, and 33) is a U-shaped bracket 441 which is similar to the bracket 66 of the opening unit B, previously referred to, and which is secured to the frame structure of the outlet conveyor 253 in the same manner as bracket 66 is secured to the frame structure of the inlet conveyor 67 (Fig. 24).

The U channels 434 and 437 are arranged in such a manner (Fig. 34) that channels 435 and 436 are in longitudinal alignment with respect to each other with the web portions 443 and 444 thereof disposed at opposite sides. The rear portion of the U channel 434 is bent inwardly, as shown at 445 and the rear end 446 thereof is secured to the U channel 436 in any desired manner, such as welding or the like. The front end of the U channel 437 is bent inwardly, as shown at 447 and the rear end 448 thereof is secured to the U channel 435 in any convenient manner. Mounted upon the frame structure 433 is a conveyor table 449 comprising a front portion 450 and a rear portion 451. The front portion 450 is formed by a pair of L channels 452 and 453 arranged adjacent each other in spaced and parallel relation with the flanges 455 and 456 thereof horizontally disposed and forming a longitudinally extending table surface 457 while the vertically disposed flanges 458 and 459 of the channels 452 and 453, respectively, form the guide walls of the table portion 450.

The rear portion 451 of the conveyor table 459 (Figs. 28, 30, and 35) is formed by a pair of L channels 461 and 462 which are arranged in spaced and parallel relation with their flanges 463 and 464 horizontally disposed and forming a longitudinally extending table surface 465 while the vertically extending flanges 466 and 467 of the L channels 461 and 462, respectively, form the guide walls of the rear table portion 451. The L channels 452, 453, and 461, 462 are firmly secured to the frame structure 433 in such a manner that the horizontal flange 463 of the L channel 461 (Fig. 28) forms the continuation of the horizontal flange 456 of the L channel 453, while the L channels 452 and 462 are disposed in spaced and parallel relation at opposite sides thereof. The vertical flange 459 of the L channel 453 ex-

tends beyond the rear end 468 of the horizontal flange 456 and is curved outwardly terminating at 469 (Fig. 28). The front end of the horizontal flange 464 of the L channel 462 is fitted against the curved portion of the vertical flange 459 of the L channel 453, as shown at 470, while the front end of the vertical flange 467 of the L channel 462 is curved outwardly, as shown at 471, and is joined to the rear end 469 of the flange 459 to form a continuous guide wall therewith. A gusset plate 472 is welded to the flanges 459, 467, and 464 so as to close the open space at the junction of the flanges 459 and 467.

The rear end of the horizontal flange 455 of the L channel 452 is curved, as shown at 473, and the vertical flange 453 is curved inwardly toward the channel 451, as shown at 474, and extends backwardly, as illustrated at 475, terminating at 476, while the front portion of the vertical flange 466 of the L channel 461 is cut away and the rear portion thereof is joined with the rear end 476 of the flange 458 so as to form a continuous guide wall therewith. The horizontal flanges 455, 456, and 463 of the L channels 452, 453, and 461, respectively, are so arranged with respect to each other as to provide an opening 477 extending longitudinally of the table surface 457. Likewise, the horizontal flanges 463 and 464 of the L channels 461 and 462 are arranged in spaced relation so as to provide an opening 478 extending longitudinally of the table surface 465.

From the above it will, therefore, be seen that the horizontal flanges of the L channels 452, 453, and 462, 463 form a continuous conveyor table provided with guide walls at the sides thereof established by the vertical flanges of said channels so that a trough or channel is formed along which the cartons are advanced in the manner as hereinafter described. The front portion of the conveyor trough is of sufficient width to receive the cartons endwise therein while the rear portion of the trough is considerably wider to permit advancement of the cartons sidewise therein. It will be further noted that due to the disposition of the various L channels and the configuration of their flanges a curved pathway is formed intermediate the front portion 450 of the conveyor table 449 and the rear portion 451 thereof so that the cartons received by the front portion of the conveyor table are gradually switched over to the rear portion of the table during their conveyance therealong. The front portion 450 of the conveyor table (Fig. 1) is preferably of considerable length so as to serve as an inspection table enabling an operator standing beside the same to inspect the cartons and remove improperly filled cartons or damaged cartons from the machine during the continuous operation thereof.

Secured to the lower flanges of the U channels 434 and 435 (Figs. 29 and 33) substantially halfway between the front and rear ends of the frame structure 433 is a yoke 481, while attached to the lower flanges of the U channels 436 and 437 at the rear end of the frame structure 433 is a yoke 482 (Figs. 29, 30, and 35). Secured to the yokes 481 and 482 are standards 483 and 484, respectively, provided with flanges (not shown) at their lower ends by which the standards are secured to the floor or foundation on which the machine is placed whereby the conveyor mechanism 425 is firmly supported at the desired height so as to form a continuation of the arcuate table 367 of the outlet conveyor 253.

The bracket 441, previously referred to (Figs.

31 and 32), is provided with bearings 486 and 487 within which a transverse shaft 488 extending through openings 489 and 490 in the web portions of the U channels 434 and 435 is rotatably mounted. Fixed to the shaft 488 for rotation therewith and disposed intermediate the bearings 486 and 487 is a sprocket 491, while keyed to the free end 488a is a sprocket 492 comprising a flanged hub portion 493 and a body portion 494 adjustably secured relative to each other by means of a slot and cap screw arrangement 495, well known in the art to permit rotative adjustment of the sprocket 492 relative to the shaft 488.

Secured to the U channels 434 and 437 (Fig. 34) are bearings 497 and 498 within which a transverse shaft 499 is rotatably mounted. This shaft extends through openings 500, 501, and 502 in the web portions of the U channels 434, 436, and 437 and is provided with retaining collars 503 and 504 fixed thereto and bearing against the web portions of the U channels 434 and 437, respectively, for maintaining the shaft 499 in proper position within the bearings 497 and 498. Fixed to the shaft 499 is a sprocket 505 and trained around the same and the sprocket 491 (Figs. 33 and 34) is an endless conveyor chain 506 provided with a plurality of pusher members 508 spaced with respect to each other a distance in excess of the length of the cartons to be handled thereby. These pusher members extend upwardly through the opening 477 of the table portion 450 a sufficient distance above the table surface 457 so as to engage the cartons supported upon the same and to advance them therealong in the manner as will be described later on.

Trained around the sprocket 492 and a sprocket 492a keyed to the drive shaft 226 (Fig. 1) of the filling unit C is an endless drive chain 509 so that upon operation of the shaft 226 the shaft 488 and sprocket 491 are continuously driven and the conveyor chain 506 is continuously operated in the direction of arrow 510 (Figs. 1, 28, 33, and 34). Secured to the transverse braces 438 directly below the upper run of the conveyor chain 506 intermediate the sprockets 491 and 505 is a chain guide 511 (Fig. 33) for supporting the upper run of the conveyor chain in horizontal position and to prevent sagging thereof.

Secured to the U channels 434 and 437 intermediate the shafts 488 and 499 are bearings 514 and 515 within which a transverse shaft 516 is rotatably mounted. This shaft extends through openings 517, 518, and 519 in the web portions of the U channels 434, 435, and 437 and fixed to the same are retaining collars 520 and 521 engaging the web portions of the channels 434 and 437 for maintaining the shaft in proper position within the bearings 514 and 515. Fixed to the end 516a of the shaft 516 is an adjustable sprocket 522 (Figs. 28, 29, and 34) which is of the same construction as the sprocket 492, previously referred to. Trained around the sprocket 522 and a sprocket 523 keyed to the shaft 499 is an endless chain 524 (Figs. 29 and 34). Fixed to the shaft 516 for rotation therewith is a sprocket 525 and trained around the same and a sprocket 526 (Figs. 30, 38, and 39) keyed to a transverse shaft 527 at the rear end of the frame structure 433, is an endless conveyor chain 528 provided with a plurality of spaced pusher members 529.

The pusher members 529 extend upwardly through the longitudinally extending opening 478 of the rear portion 451 of the conveyor table 75 449 and project a sufficient distance above the

table surface 465 so as to engage the cartons supported thereon and to advance the same therewith upon operation of the conveyor chain 528. The pusher members 529 are spaced with respect to each other sufficiently so as to receive the cartons sidewise therebetween.

Secured to the rear end of the U channels 436 and 437 of the frame structure 433 by means of bolts 530 (Figs. 28, 29, 38, and 39) are castings 531 and 532 which form a part of the frame structure of the carton discharge and presser unit E. The front ends of these castings which overlie the web portions of the U channels 436 and 437 are provided with bearings 533 and 534 within which the transverse shaft 527, previously referred to, is rotatably mounted. The end portions 535 and 536 of the shaft 527 disposed within the bearings 533 and 534 are of reduced diameter so that shoulders 537 and 538 are formed which engage the inner side of the castings 531 and 532, respectively, whereby the shaft is maintained in proper position within the bearings 533 and 534.

Mounted upon the transverse braces 439 directly below the upper run of the conveyor chain 528 (Fig. 30) is a chain guide 539 which maintains the upper run of the conveyor chain 528 in substantially horizontal position and prevents sagging of the same.

Rotatably mounted within bearing portions 540 and 541 (Fig. 38) of the castings 531 and 532 is a transverse shaft 542 to which a roller 543 is fixed for rotation therewith. Fixed to the free end 542a of the shaft 542 is a sprocket 544 and trained around the same and a sprocket 545 fixed to the reduced end of the shaft 527 is an endless drive chain 546.

From the above it will, therefore, be seen that upon operation of the conveyor chain 506 and shaft 499, shaft 516 is driven simultaneously therewith in view of the driving connection established by means of the sprockets 523, 522, and chain 524. The rotation of the shaft 516 and sprocket 525 effects operation of the conveyor chain 528 in the direction of arrow 547 (Figs. 30 and 34) so that the pusher members 529 of the upper run of the chain 528 are caused to travel continuously toward the discharge unit E and effect advancement of the cartons along the rear portion 451 of the conveyor table 449.

Fixed to the castings 531 and 532 are further transverse rods 548 and 549 upon which transverse rolls 551 and 552 are rotatably mounted. Trained around the rolls 543, 551, and 552 is an endless conveyor belt 553, the upper run 554 of which is disposed in substantially horizontal alignment with respect to the table surface 465 of the rear portion 451 of the conveyor table 449.

Upon operation of the conveyor chain 528, in the manner previously referred to, shaft 527 will be rotated therewith and effects a corresponding rotation of the shaft 542 and roll 543 through sprockets 545, 544, and drive chain 546. The rotation of the roll 543 in the direction of arrow 555 (Fig. 30) effects travel of the conveyor belt 553 in the direction of arrow 556 (Fig. 30) and a corresponding rotation of the rolls 551 and 552 therewith so that the cartons which arrive at the rear end of the conveyor table 449 are transferred by the pusher members 529 upon the conveyor belt 553 and are advanced thereby through the carton discharge and presser unit E. The transverse rod 549 is adjustably disposed in slots 531a and 532a to permit adjustment of the roll

552 for taking up any slack in the conveyor belt 553.

Mounted above the castings 531 and 532 by means of adjustable vertical supporting straps 557, 558, 559, and 560 are horizontally disposed supporting members 561 and 562 arranged in spaced relation a predetermined distance above the castings 531 and 532. Fixed within the supporting members 561 and 562 (Figs. 29, 38, and 39) are a plurality of transverse rods 563, 564, 565, and 566 disposed in spaced relation with respect to each other upon which presser rolls 567, 568, 569, and 570 are rotatably mounted. These presser rolls extend transversely with respect to the conveyor belt 553 and are disposed a predetermined distance above the same, i. e., a distance corresponding to the height of the cartons so that the rolls 567 to 570 engage the upper surface of the cover 7 of the cartons and exert a slight downward pressure upon the same to effect a complete closing of the cover and interlocking of the straight edges 25 and 26 of the tabs 22 and 23 with the locking flap 24. The rolls 568, 569, and 570 are in vertical alignment with the rolls 543, 551, and 552, respectively, and the transverse rod 566 is adjustable within slots 571 and 572 (Figs. 29 and 30) of the members 561 and 562 so that the roll 570 may be adjusted and maintained in correct alignment with the roll 552 upon adjustment of the latter, as previously stated herein.

Secured to the front portion of the U channel 437 (Figs. 28 and 34) and the inwardly bent portion 447 thereof is a cover plate 575 (Fig. 28) provided with a slot 576 which forms the continuation of the opening 478 of the rear portion 451 of the conveyor table 449 so that the plate 575 will not interfere with the operation of the pusher members 529 of the conveyor chain 528. Likewise, the vertical flange 459 (Fig. 48) is cut out, as shown at 577, so as to permit travel of the pusher members 529 past this flange without interfering therewith.

Fixed to the plate 575 (Figs. 28, 29, and 48) is a vertically disposed pivot stud 579 upon which a carton turning arm 580 is freely pivoted by means of a sleeve like hub portion 581 provided with a radially extending pin 582 to which one end of a coil spring 583 is attached, the other end of which is secured to the plate at 584. The carton turning arm 580 extends over the vertical flange 459 of the L channel 453 into the path of the cartons on the conveyor table 449 and engages the cartons about half way between the top and the bottom thereof. To permit the extension of the arm 580 over the flange 459 the height of the latter is sufficiently reduced, as clearly shown in Fig. 48. The arm 580 is normally held in the position shown in Fig. 28 in which it abuts 60 against an abutment 585 adjustably carried by the plate 575 by means of a bolt and slot arrangement 586. The free end 580a of the carton turning arm 580 is angularly disposed with respect to the remaining portion of the arm and adapted 65 to engage the front end 12 of each carton during its transfer from the front portion 450 of the conveyor table to the rear portion 451 thereof and to effect the turning of the cartons from lengthwise to sidewise position so that they are subsequently advanced sidewise past the flap opening mechanism 427 and the cover closing mechanism 428 into the discharge and presser unit E.

It is further to be noted that the inwardly curved and rearwardly extending portions 474 and 475 of the flange 458 of the L channel 453

(Fig. 30) are provided with a cut out portion 587 so as to provide sufficient clearance for the pusher members 508 and to prevent interference thereof with the guide wall 458.

Secured to the flange 458 of the L channel 452 (Figs. 1, 29, and 33) by means of a plurality of supporting brackets 588 is a cover supporting rod 589 which forms a continuation of the rod 385 of the filling machine and extends first in a curved path along the conveyor table 367 of the outlet conveyor 253, and then a straight path parallel to the front portion 450 of the conveyor table. The rear end of the rod 589 is curved inwardly toward the rear portion 451 of the conveyor table 449, as shown at 590 in Fig. 28. This rod 589 is disposed exterior of the front portion 450 of the conveyor table 449 and is arranged in spaced relation relative to the guide wall 458 in horizontal and vertical directions (Fig. 31) so that when a carton is advanced endwise along the table portion 450 the open cover or lid of the carton F is supported by the rod 589.

Secured to the web portions of the U channels 436 and 437 of the frame structure substantially halfway between the carton discharge and presser unit E and the carton turning finger 580 (Fig. 35) are turret supporting brackets 595 and 596, respectively. Both of these brackets are of identical construction and each comprises a horizontally disposed bearing portion 597 and a vertically disposed bearing portion 598. Rotatably mounted within the bearing portions 597 and extending transversely of the machine below the frame structure 433 is a shaft 599 provided with a bevel gear 600 at each of its ends. The bevel gears 600 are fixed to the shaft 599 for rotation therewith and are adapted to intermesh with bevel gears 601 and 602, respectively. The bevel gear 601 is fixed to a vertically disposed shaft 603 which is rotatably mounted within the bearing portion 598 of the turret supporting bracket 595 and keyed to the upper end of the shaft 603 is a turret 605 provided with a plurality of spider arms 606. The bevel gear 602 (Fig. 35) is fixed to a vertical shaft 607 rotatably mounted within the bearing portion 598 of the turret supporting bracket 596 and fixed to the upper end of the shaft 607 for rotation therewith is a turret 608 provided with a plurality of spider arms 609.

Rotatably mounted adjacent the outer end of each of the spider arms 606 and 609 of the turrets 605 and 608, respectively (Fig. 36), are pivot pins 610, the lower portion 611 of which is of reduced diameter so that a shoulder 612 is formed engaging a bearing surface 613 of the spider arms, while secured to the lower end of the reduced portion 611 of each pin is a retaining collar 614 for maintaining the pivot pin 610 in position without preventing free rotation thereof. Pivotally secured to the upper end of each pivot pin 610 by means of a transverse pivot pin 615 is a flap or flange opening arm 616 provided with a hook 617 (Figs. 28 and 48) at its outer end. Secured to the rear end of each arm 616 adjacent the pivot 610 is one end of a coil spring 618, the other end of which is attached to a stud 619 fixed to the turrets 605 and 608.

From the above it will, therefore, be seen that the turret arms 616 are mounted for universal movement on the spider arms 606 and 609, but are normally held in substantially horizontal position radially disposed to the turret structure with which they are associated and in alignment with the spider arms thereof by means of the coil springs 618. The springs 618 of opposing

turrets are secured to the studs 619 at different heights (Fig. 35) so that the arms 616 of the turret 605 are slightly downwardly inclined and the arms 616 of the turret 608 are slightly upwardly inclined with respect to horizontal and will not interfere with each other upon rotation of the turrets. Fixed on the turrets 605 and 608 adjacent each stud 619 is a cover engaging and supporting arm 625. One arm 625 is associated with each flange opening arm 616 and is disposed in spaced and fixed relation with respect thereto at the hook side of each flange opening arm.

Each turret is preferably provided with four spider arms, four flange opening arms, and four cover engaging and supporting arms. If desired, however, the number of the same may be increased or reduced, as will be obvious to those skilled in the art. The turrets 605 and 608 are so disposed and in such rotative adjustment with respect to each other that the arms 616 and 625 of opposing turrets cooperate with each other during the rotation of the turrets.

Fixed to the shaft 599 (Figs. 29, 30, and 35), previously referred to, is a sprocket 626, and trained around the same and a sprocket 627 fixed to the shaft 499 (Figs. 30 and 34) is an endless drive chain 628 so that upon rotation of the shaft 499 the shaft 599 is rotated in timed relation therewith and rotation of the turrets 605 and 608 in timed relation and in opposite directions, i.e., in the direction of arrows 629 and 629a (Fig. 28) is obtained.

Arranged intermediate the turrets 605 and 608 and the carton discharge and pressure unit E (Figs. 28, 29, 30, 35, and 37) is the cover closing unit 428 which is supported above the rear portion 451 of the conveyor table 449 by means of a supporting bracket 630 fastened to the flange 466 of the L channel 461 and the web portion of the U channel 436 by means of cap screws 631. The bracket 630 is of L-shaped construction and the leg portion 632 thereof extends transversely of the rear portion 451 of the conveyor table 449 at a predetermined distance above the same. Secured to the portion 632 is a cover guide and closing plate 633 which comprises a horizontally disposed downwardly extending portion 635, a horizontally disposed rearwardly extending portion 636, the rear end 637 of which is inclined downwardly toward the presser roll 567, and terminates in a horizontally disposed portion 638 adjacent the same. Secured to the cover guide plate 633 intermediate the portions 635 and 636 thereof is a bar 639 which extends transversely with respect to the conveyor mechanism of the machine. Rotatably mounted on the free ends of the bar 639 by means of screws 640 are cover closing rolls 641 and 642 which are adapted to engage the cover of the carton and fold the same over the carton to partially close the same (Fig. 51) during the advancement of the cartons therewith while the downwardly inclined portion 637 of the cover guide plate 633 effects the final closing of the cover of the carton and guides the same beneath the first presser roll 567 so as to assure correct introduction of the carton into the pressure and discharge unit E.

During the initial cover closing operation, as shown in Fig. 51, the lower portions of the end flaps of the cover are disposed outside the guide walls 466 and 467 of the conveyor table 449 and must be introduced into the guide channel of the conveyor before the cover can be completely closed. To obtain the introduction of the end flaps of the cover of the carton into the conveyor

channel the guide walls 466 and 467 are cut open, as shown at 644 and 645 (Figs. 28, 29, 50, and 51), and the portions of the guide walls adjacent said cuts are bent outwardly, as shown at 646 and 647, respectively, so that openings 648 and 649 are formed. These outwardly bent portions 646 and 647 of the guide walls facilitate the introduction of the end flaps of the carton cover through the openings 648 and 649 into the conveyor channel incident to the cover closing operation and the advancement of the cartons therewith.

Secured to the bracket portion 632 of the cover closing station 428 is a brush supporting arm 650 (Figs. 28, 29, 30, and 35) which extends rearwardly above the rear portion 451 of the conveyor table 449 in spaced relation thereto and parallel to and above the path of travel of the pusher members 529. Secured to the free end of the arm 650 is a brush 651 which extends longitudinally of the front portion of the arm parallel to the path of travel of the pusher members 529. The brush 650 is provided with downwardly extending comparatively long and soft bristles 652 which are adapted to engage the open cover 13 (Fig. 47) of the carton and to position the same correctly for introduction thereof between the cooperating arms 616 and 625 of the turrets 605 and 608, as will be more fully described later on. The brush 651 is positioned at such height above the conveyor table 449 that the bristles 652 engage only the upper edge 13a of the open cover 13 and exert only a slight pressure or backward drag against the same to thereby gently tilt the cover 13 into the desired position while the cartons are advanced beneath and past said brush.

Operation of carton closing and discharge units

During the operation of the machine the shaft 488 of the closing unit is continuously driven by the drive shaft 226 of the filling unit C by means of the sprockets 492a, 492, and sprocket chain 509 whereby continuous operation of the conveyor chains 506 and 528 and the discharge belt 553 in the direction of arrows 510, 547, and 556 (Figs. 28, 30, and 33) is effected, while the turrets 605 and 608 are continuously rotated in the direction of arrows 629 and 629a (Fig. 28) in timed relation therewith.

The filled cartons, having their covers disposed in open position, are received endwise from the outlet conveyor 253 of the filling unit C by the front portion 450 of the conveyor table 449 (Fig. 8) and are advanced endwise in spaced relation and in a single file along the same by the pusher members 508 while the open covers of the cartons are supported by and slide along the cover supporting rod 589. As each carton approaches the bent portion 660 (Fig. 43) of the conveyor trough, the edge 661 of the body portion 6 of the carton engages and travels along the inwardly curved portion 474 of the guide wall 458 whereby the filled carton F is turned and shifted into a position, as shown in Fig. 43, in which the end wall 12 of the carton engages the carton turning arm 580, as shown at 662. As soon as the carton arrives in this position, and while the pusher member 508 engaging the end wall 11 of the carton continues its forward movement in the direction of arrow 663 (Fig. 43), the carton is further advanced and, since its forward movement is retarded by the arm 580, the carton is turned from its position, shown in Fig. 43, first to the position shown in Fig. 44 and finally to the position illustrated in Fig. 45

by the combined action of the pusher member 508 and arm 580 and is gradually transferred from the portion 450 to the portion 451 of the conveyor table 449. To facilitate easy turning of the carton in the manner above described, the carton engaging portion of the pusher members 508 are preferably made cylindrical, as shown in Fig. 33.

In view of the force applied by the pusher member 508 which tends to urge the carton forwardly along the conveyor table 449, the arm 580 is depressed from the position shown in Fig. 43, to the position in Fig. 44, and finally to the position as shown in Fig. 45 against the tension of the coil spring 583 so that while the end wall 11 of the carton is advanced by the pusher member 508 the forward movement of the end wall 12 of the carton is retarded and the carton is pulled toward the curved guide wall portion 470 of the guide wall 459 and the corner 665 of the body portion 6 of the carton (Figs. 44 and 45) enters into the outwardly projecting corner 666 of the conveyor channel formed by the outwardly curved portions 470 and 471 of the guide walls 459 and 467. This outwardly extending corner 666 of the conveyor channel provides sufficient room for the carton to turn from endwise to substantially side-wise position.

While the carton is now in the position as shown in Fig. 45, one of the pusher members 529 of the conveyor chain 528 engages the side wall 10 of the body portion 6 of the carton and exerts a forward pressure upon the same in the direction of arrow 667 (Fig. 45) whereby the carton is further turned in counterclockwise direction and its end wall 11 is disengaged from the pusher member 508 of the conveyor chain 506, while the end wall 12 of the carton bears against the angularly disposed portion 580a of the arm 580 and pivots about the same. Consequently, in view of the forward movement imparted to the carton by the pusher member 529 and the pivotal movement of the carton about portion 580a of the arm 580, the carton is turned into complete side-wise position within the conveyor channel, as shown in Fig. 46, and is now advanced by the pusher member 529 along the rear portion 451 of the conveyor table 449, while the end wall 12 of the carton disengages from the arm 580 which thereupon returns to its original position into contact with the abutment 585 under the urge of the coil spring 583.

The spacing of the pusher members 508 and 529 and the speed of travel of the conveyor chains 506 and 528 are such as to effect the correct turning of the carton and its transfer from the front portion 450 to the rear portion 451 of the conveyor table 449 without interference by the pusher members 508 and 529.

While the carton is now advanced along the rear portion 451 of the conveyor table 449 with the open cover 7 disposed in upwardly inclined and leading position, the brush 651 engages the upper edge 13a of the cover and tilts the same slightly backward to the position, as shown in Fig. 47, so that as the carton now approaches and moves past the continuously rotating flange or flap opening turrets 605 and 608, the cover 7 is held in such position that it will be received between the opposing arms 616 and 625 of the turrets which are rotated in the directions of arrows 629 and 629a, respectively, and in such timed relation with respect to the conveyor chain 528 and the carton advanced thereby that the cover 7 of the carton will freely enter the space

between these arms, as shown in Fig. 47. While the advancement of the cartons and the rotation of the turrets 605 and 608 continues, the cover is turned forward by the combined action of the opposing pairs of arms 616, 625 into the position as shown in Figs. 48 and 49 at which time the cooperating arms 616 of the turrets are disposed substantially parallel to each other with the hook portions 617 thereof disposed above each other and contacting the inner surface of the lid portion 13 of the cover (Fig. 49). During further advancement of the carton from the position shown in Fig. 49 to the position illustrated in Fig. 50 and while the turrets 605 and 608 continue their rotation in the direction of arrows 629 and 629a, respectively (Fig. 50), the hook portions 617 of the arms 616 engage the end flaps 14 and 15 of the carton and pull them outwardly thereby erecting the same. In view of the fact that the side flap 16 is connected with the end flaps 14 and 15 and folded over the same, it is also erected incident to the erection of the end flaps 14 and 15. As the advancement of the carton by the pusher member 529 and the rotation of the turrets 605 and 608 in the direction of arrows 629 and 629a, respectively (Fig. 50), continues, the lower portion of the end flaps 14 and 15 is pulled outwardly beyond the guide walls 466 and 467 by the hooks 617 of the arms 616 in the manner as clearly shown in Fig. 50, while the arms 616 of the turrets pivot relative to the spider arms supporting the same against the tension of the springs 618 into the position as shown in Fig. 50 and are maintained in engagement with the end flaps 14 and 15 by the action of the springs 618.

As soon as the carton arrives in the position illustrated in Fig. 50, the cover closing rolls 641 and 642 of the cover closing mechanism 428 engage the outer surface of the cover 13, and as the carton continues to travel in the direction of arrow 668 (Figs. 50 and 51) they begin to close the cover, i. e., to swing the same downward in the direction of arrow 670 (Figs. 50 and 51). As soon as the carton has passed the position as shown in Fig. 50, the turret arms 616 disengage from the end flaps 14 and 15 of the cover which now snap back so that the lower portions of these flaps engage the outer surfaces of the guide walls 466 and 467 substantially as shown at 671 in Fig. 51, while the arms 616 swing back into radial positions with respect to their turrets under the action of the coil springs 618. As the carton now continues its advancement with the lower ends of the end flaps 14 and 15 sliding along the outer side walls of the guides 466 and 467 (Fig. 51), the cover 7 is closed further by the rolls 641 and 642 and, as soon as the lower portions 672 of the end flaps are adjacent the openings 648 and 649 of the guide walls 466 and 467 and travel past the same, they are guided back into the conveyor trough by the flap guides 646 and 647. With the end flaps of the cover now disposed within the conveyor channel the cover of the carton is closed by the rear end 637 of the cover guide plate 633 in the manner as diagrammatically illustrated in full and dotted lines in Fig. 51 and the carton is thereupon introduced into the carton discharge and presser unit E and transferred upon a conveyor belt 553 thereof by the pusher member 529. The carton is now advanced by the conveyor belt 553 past the presser rolls, 567, 568, 569, and 570 and is subsequently discharged from the machine. The presser rolls 567 to 570 are so adjusted relative to the rear end of the conveyor

table 449, rolls 543, 551, 552, and the belt 553 as to exert in cooperation with the rear end of the closing plate 633 sufficient pressure upon the cover of the carton to completely close the same and to interlock the straight edges 25 and 26 of the tabs 22 and 23 with the locking tab 24. While the carton is advanced by the discharge belt 553 between the rolls 543, 551, 552, and presser rolls 567 to 570 it is pressed into shape to eliminate any bulging of the bottom or cover of the carton. The cover is now completely closed and held in locked position on the body portion of the carton and is prevented from opening during discharge of the carton from the machine and subsequent handling, such as wrapping or labeling thereof. In the continuous operation of the carton closing discharge unit of the machine the cartons are continuously advanced in a single file and in spaced relation along the conveyor table 449 and 20 are discharged from the discharge and pressure unit E and the operations described herein in connection with a single carton are repeated with respect to each carton advanced through the machine.

25

No carton no fill control mechanism

The no carton no fill control mechanism G (Figs. 1, 22, and 23) is associated with the carton opening unit B and comprises a bracket 675 secured to the web portion 53 of the U channel 42 provided at its upper end with a yoke 676 within the lower portion 676a of which a bell crank 677 is rotatably mounted by means of pivot pins 678. One arm 679 of the bell crank is horizontally disposed and provided with a weighted actuating shoe 680 which extends into the path of the upper edge of the end walls 12 and 11 and the side wall 10 of the cartons traveling along the conveyor table 101 of the opening unit B and is normally disposed in its lowermost position, as shown in Fig. 23, when the machine is empty. The other arm 681 of the bell crank 677 is vertically disposed, i. e., at right angles to the arm 679 and is provided with a single tooth 682 at its upper end.

The actuating shoe 680 includes a straight center portion 683 and upwardly inclined guide portions 684 and 685 at opposite ends thereof so that as the first carton is advanced past the same 50 the shoe is gradually lifted to its elevated position upon contact with the upper edge of the end wall 12 and side wall 10 of the carton and is gradually lowered to its original position after the last carton has passed the same and the inclined guide 685 is disengaged from the upper edge of the side wall 10 and end wall 11. The center portion 683 of the shoe is of sufficient length to bridge the gap between adjacent cartons of a continuous uninterrupted file thereof 55 traveling along the conveyor table 101 so that the shoe is continuously held in elevated position by the upper edge of the side wall 10 of the cartons as long as the cartons travel in uninterrupted position therewith and will only drop back to its original or lowermost position if a carton is missing, is not completely opened, or if the last carton advanced from the magazine A has passed the same.

Pivotedly mounted within the upper portion 70 676b of the yoke 676 by means of pivot pins 686 is a mercury switch holder 687 provided with a downwardly extending arm 688 having a slot 689 at its lower end within which the tooth 682 on the free end of the arm 681 of the bell crank 677 is received. The switch holder is further

provided with spring clips 690 for holding a mercury switch 691 in firm position thereon. The arm 688 is disposed in such angular relation with respect to the holder 687 and switch 691 that when the shoe 680 is in elevated position the mercury switch is tilted to closed position and when the shoe is in its lowermost position the mercury switch 691 is disposed in open position. Limit stops 692 and 693 secured to the bracket 675 adjacent the bell crank arm 681 limit the movement of the latter to prevent tilting of the mercury switch and to limit the downward movement of the shoe 680. A cover 694 removably secured to the supporting bracket 675 in any convenient manner encloses the entire control mechanism G and protects the same against damage.

Associated with the mercury switch 691 is a motor control circuit 697 (Fig. 52) provided with two stop switches 698 and 699 and a stop and start switch 700. The stop switch 698 is mounted at the front end of the frame structure of the machine near the magazine A, while the stop switch 699 is mounted at the rear end of the frame structure of the machine adjacent the carton turning station. The stop and start switch 700 is preferably mounted on the frame structure of the machine adjacent the no carton no fill control mechanism G and a toggle switch 701 disposed adjacent the control mechanism G and associated with the control circuit 697 is further provided for shorting the mercury switch 691 if it is desired to run the machine empty.

The control circuit 697 is connected to a magnetic switch 702 which in turn is connected with the source of electric energy LI, LII, LIII, and the motor 229, previously referred to. In the drawings a three phase motor and a three phase power supply line have been shown. The mercury switch, stop switches, stop and start switch, toggle switch, and magnetic switch are all of conventional construction and a specific description thereof is therefore not given herein. Likewise, a specific description of the wiring diagram has been omitted since its arrangement is obvious from Fig. 52.

Operation of no carton no fill control mechanism

When the machine is empty and not in operation, the actuating shoe 680 of the no carton no fill control mechanism G is in its lowermost position (Fig. 23) and the mercury switch 691 and toggle switch 701 are in open position. To start the machine, the operator swings the toggle switch 701 (Fig. 52) to closed position whereby the mercury switch 691 is shorted and thereupon presses the start button 703 of the start and stop switch 700. This closes the circuit formed by wires LI, I, LIII, and II whereby the solenoid 704 of the magnetic switch 702 is energized effecting closing of the four contacts 705 of the magnetic switch so that the motor terminal wires IV, V, and VI are connected to the power lines LI, LII, and LIII and motor 229 is started effecting operation of the machine. As soon as the solenoid 704 has been energized and the pressure on the start button of switch 700 is released, wire II is disconnected and the machine is now under the control of circuit I, III.

Upon the operation of the machine the cartons are fed in a continuous uninterrupted flow from the magazine A along the conveyor I and as soon as they travel past the shoe 680 the same is elevated whereby the mercury switch 691 is tilted to closed position. The toggle switch 701 is now swung to open position so that the circuit I, III

is now under the control of the mercury switch 691. Therefore, if the continuous flow of the cartons past the shoe 680 is interrupted due to a missing or not fully opened carton or exhaustion of the supply of cartons in the magazine, the shoe will immediately drop to its lowermost position whereby the magnetic switch is opened, the solenoid 704 is de-energized and the magnetic switch contacts 705 are opened cutting off the power supply to the motor 209 so that the entire machine is immediately stopped. In this way discharge of material from the volumetric measuring cups when no carton is in receiving position therebeneath is prevented.

It is further apparent that by pressing the button of the stop switches 689 or 699, or by pressing the stop button 706 of the start and stop switch 700, the operation of the machine may be manually stopped whenever desired.

The machine is started again by pressing the start button 703 of the switch 700 provided, of course, that the mercury switch has not been opened due to lack of cartons or any interruption in the continuous flow thereof, because in such latter case the toggle switch 701 has first to be closed before the start button 703 of the switch 700 is depressed. After the machine has been restarted by manipulation of the switches 701 and 700, the toggle switch 701 is again opened as soon as the continuous flow of the carton past the shoe 680 has been resumed, whereupon the machine is again under the automatic control of the no carton no fill mechanism G.

Résumé of operation of entire machine

In the above description of the construction of the machine, the operation of the various parts thereof has been specifically explained. However, for a more complete understanding a brief résumé of the operation of the entire machine will now be given wherein the function of the various units will be set forth in proper sequence and timed relation.

Before the operation of the machine is started, the magazine A is filled with collapsed cartons and the hopper 315 of the filling unit C is supplied with material to be filled into the cartons. The motor 398 is set into operation, the toggle switch 701 is closed, and the start button 703 of the switch 700 is depressed whereby the operation of the machine is started, as specifically explained in the above.

During the operation of the machine, the cartons are conveyed endwise from the magazine A in continuous and uninterrupted flow along the conveyor I of unit B past the cover turning mechanism 2 which turns the covers to open position and the carton opening mechanism 3 which opens and blocks the body portions of the cartons. As the blocked cartons, with their covers disposed in open position and resting on the supporting rod 219, travel past the actuating shoe 680, the same is elevated thereby and the mercury switch 691 is tilted to closed position. The operator now opens the toggle switch 701 so that the entire machine, with the exception of the motor 398, is under the automatic control of the no carton no fill mechanism G, i. e., the mercury switch 691 thereof. The blocked cartons are thereupon fed endwise into the inlet conveyor 67 which presents the same to the feed ring 362 of the filling machine 252. The feed ring 362 advances the cartons through the filling machine in such a manner that each carton is in alignment with a volumetric measuring pocket of the continuously

rotating table 340 and travels in timed relation therewith. During the rotation of the table 340 the volumetric measuring pockets 348 receive a measured quantity of material from the supply hopper 375 and discharge the same into the cartons aligned therewith after the measuring pockets and cartons pass the rear end of the valve plate 381. The portion of the conveyor table 364 adjacent the rear end of the valve plate 381 is continuously vibrated by the motor 398 so as to facilitate the discharge of the material from the measuring pockets 348 to the cartons and to level out the material deposited into the same.

The filled cartons with their covers still disposed in open position and resting upon the supporting rod 385 are thereupon received by the arcuate cover 253 and are transferred thereby from the filling machine onto the conveyor 425 of the carton closing unit D which conveys them endwise toward the carton turning station 426 while the open covers are supported upon the cover supporting rod 389. At the turning station 426 the cartons are turned from endwise to side-wise position relative to the conveyor 425.

During the travel of the cartons from the outlet conveyor 253 toward the carton turning station 426 along the comparatively long front portion 450 of the conveyor 425, which serves as an inspection table, the filled cartons are inspected by the operator and any improperly filled or damaged cartons are removed from the machine without stopping the operation thereof.

While the cartons now disposed sidewise with respect to the conveyor 425 are advanced along the same with the covers in leading position, they travel past the flange opening and carton closing stations, i. e., the continuously rotating turrets 605 and 608, and the closing rolls 641 and 642, and plate 633. The arms of the turrets 605 and 608 engage the flange of the cover and open the same while the closing rolls 641 and 642 and plate 633 fold the cover upon the carton body and subsequently close the same with the edges 25 and 26 of the carton in interlocking engagement with the locking flange 24.

The closed cartons are thereupon introduced into the discharge and presser unit E where they are pressed into shape and finally discharged from the machine. In the event the supply of the cartons in the magazine A is exhausted and the machine runs empty, or if a carton is not completely opened, or a carton is missing in the continuous file thereof, the actuating shoe 680 adjacent the conveyor I drops immediately to its lowermost position and tilts the mercury switch 691 to open position so that the circuit I, III is interrupted and the machine is immediately stopped. Thereupon, after the operator has replaced a not fully opened carton or has manually placed any missing cartons on the conveyor I and, if necessary, refilled the magazine A, the machine may again be started for further continuous operation by pressing the starting button 703 of the switch 700 in the manner as previously described herein.

The machine of the present invention is especially adapted for handling the particular type of folded carton described herein which is designed for packaging frozen food products or the like. It is to be understood, however, that the utility of the machine is not limited for use in connection with the particular carton specifically described herein, since other cartons for packaging food products or other merchandise may

be effectively handled thereby provided that these cartons are folded and collapsed in a similar manner and require substantially the same operations for opening and closing the same as the specific type of carton referred to herein.

While we have shown and described a preferred apparatus and a preferred method for carrying out our invention, it will be understood that both are capable of variation and modification while still employing the principles of our invention. It is to be understood, therefore, that the scope of the invention should be limited only by the scope and proper interpretation of the claims appended hereto.

Having thus described our invention, what we claim as new and desire to protect by Letters Patents is:

1. A machine for forming, filling, and closing a carton moving in continuous and uninterrupted flow through the machine, said carton comprising a rectangular body formed by a bottom and side and end walls hinged thereto and to each other and a cover hinged to one edge of a wall of the carton body and having a continuous flange hinged on the free edges of the cover, said carton being collapsed with the side and end walls of the carton body folded flat over the bottom thereof and with the flange folded flat under the cover and the cover folded over the body of the carton and disposed in substantially the plane of the bottom of the carton, which comprises a continuous conveyor for advancing the carton in continuous and uninterrupted flow along with the predetermined path with the bottom of the carton presented downwardly and the hinge of the carton parallel to its path of travel, means associated with the conveyor for elevating and turning back the cover of the carton to expose the collapsed body portion thereof, means cooperatively associated with the conveyor for erecting the end and side walls of the carton and for blocking the carton during its travel therewith, a filling device disposed adjacent said conveyor for depositing a measured quantity of product into the blocked carton body, means for turning the filled carton on said conveyor to dispose its cover hinge normal to its path of travel, means adjacent said conveyor and engageable with the collapsed flange of a cover of the carton for opening the same during the continuing flow of the carton, means for closing the cover of the carton with the flange of the cover overlying contiguous walls of the carton, and means for driving said conveyor, body opening, filling, and flange opening means in timed relation.
2. A machine for forming, filling, and closing cartons moving in continuous and uninterrupted flow through the machine, each of said cartons comprising a rectangular body formed by a bottom and side and end walls hinged thereto and to each other and a cover hinged to one edge of a wall of the carton body and having a continuous flange hinged on the free edges of the cover, said cartons being collapsed with the side and end walls of the carton body folded flat over the bottom thereof and with the flange folded flat under the cover and the cover folded over the body of the carton and disposed in substantially the plane of the bottom of the carton, which comprises a continuous conveyor including carton receiving and advancing means, a magazine for receiving a stack of collapsed cartons with their bottoms presented downwardly and the hinge of their covers disposed parallel to the direction of travel of said advancing means whereby upon

operation of said advancing means the cartons are successively and separately received thereby, removed from the magazine and advanced along a predetermined path, stationary means associated with the conveyor for intercepting the cover of the advancing cartons and for elevating and turning back the same to expose the collapsed body of the cartons, means for opening up the collapsed carton body of each carton and for blocking the same, means disposed at a point of said conveyor for depositing a predetermined quantity of product into the blocked body of the cartons, means associated with the conveyor for intercepting the filled cartons during their continuing advancement and for effecting turning of the cartons on said conveyor to dispose the cartons with the hinge of their covers normal to the path of travel of the cartons and their covers in leading position, and means adjacent said conveyor for erecting the collapsed flange of the cover of each carton and for closing the cover upon the body of the carton with the flange of the cover disposed in overlapping relation to the walls of the carton, and means for driving the conveyor, the carton blocking, filling, and closing means in timed relation with respect to each other.

3. A machine for forming, filling, and closing a carton moving in continuous and uninterrupted flow through the machine, said carton comprising a rectangular body formed by a bottom and side and end walls hinged thereto and to each other and a cover hinged to one edge of a wall of the carton body and having a continuous flange hinged on the free edges of the cover, said carton being collapsed with the side and end walls of the carton body folded flat over the bottom thereof and with the flange folded flat under the cover and the cover folded over the body of the carton and disposed in substantially the plane of the bottom of the carton, which comprises a conveyor for advancing the carton endwise in uninterrupted flow along a predetermined path, means associated with the conveyor for opening the cover and for blocking the body of the carton during uninterrupted travel of the same, a filling device associated with the conveyor for depositing a measured quantity of product into the carton, means associated with the conveyor for turning the carton sidewise on the conveyor to dispose the cover of the carton in leading position during further travel of the carton along said conveyor, and means for closing the carton with the flange of the cover disposed in overlapping relation with respect to the walls of the carton body.

4. A machine for forming, filling, and closing a carton moving a continuous and uninterrupted flow through the machine, said carton comprising a rectangular body formed by a bottom and side and end walls hinged thereto and to each other and a cover hinged to one edge of a wall of the carton body and having a continuous flange hinged on the free edges of the cover, said carton being collapsed with the side and end walls of the carton body folded flat over the bottom thereof and with the flange folded flat under the cover and the cover folded over the body of the carton and disposed in substantially the plane of the bottom of the carton, which comprises a conveyor for advancing the carton endwise in uninterrupted flow in a single file and in spaced relation along a predetermined path, means associated with the conveyor for opening the cover and for blocking the body of the carton during uninterrupted travel of the same, a filling device

associated with the conveyor for depositing a measured quantity of product into the carton, means associated with the conveyor for turning the carton sidewise on the conveyor to dispose the cover of the carton in leading position during further travel of the carton along said conveyor, means for closing the carton with the flange of the cover disposed in overlapping relation with respect to the walls of the carton body, and means for continuously operating said conveyor, carton blocking means, filling device, and carton closing means in timed relation with respect to each other.

5. A machine for handling cartons having a rectangular body formed by a bottom and end and side walls hinged thereto and to each other and a cover hinged on one of said walls, said cartons being collapsed with the side and end walls folded flat upon the bottom and the cover folded upon the collapsed body of the carton comprising a conveyor for advancing the cartons bottoms down in a continuous and uninterrupted flow along a predetermined path, means associated with the conveyor for turning back the cover to expose the body portions of the cartons, means for engaging and erecting the end walls of the body portions whereby the side walls hinged thereto are simultaneously erected therewith and the body portions are blocked for subsequent filling thereof, and means associated with the conveyor for preventing tilting of the cartons on said conveyor during the cover turning operation.

6. A machine for handling cartons having a rectangular body formed by a bottom and end and side walls hinged thereto and to each other and a cover hinged on one of said walls, said cartons being collapsed with the side and end walls folded flat upon the bottom and the cover folded upon the collapsed body of the carton comprising a magazine for receiving a stack of collapsed cartons with their bottoms downwardly disposed, a conveyor for advancing the cartons separately from the magazine along a predetermined path, means associated with the conveyor for turning back the cover of the cartons to expose the body portion of the cartons, carton opening fingers adjacent said path for entering the exposed body portion of the cartons and for opening up the same during the continuous uninterrupted advancement of the cartons therewith, and hold down guides one each side of the conveyor for holding the body portion of the cartons in collapsed condition during the cover turning operation and for subsequently releasing the body portion of the cartons to permit opening of the same by said fingers.

7. A machine for handling cartons having their body portions collapsed with the side walls thereof folded over the end walls and the covers of the cartons overlying the same comprising a conveyor for advancing the cartons separately along a predetermined path, means associated with the conveyor for turning back the covers of the cartons to expose the body portions thereof, a hook pivotally mounted above said conveyor, means for releasing said hook for hooking engagement of the end wall at the trailing end of each carton during its travel therewith to thereby raise the same, a rotatable finger above said conveyor, and means for rotating said finger to engage and raise the end wall at the leading end of each carton during its travel therewith, whereby the end and side walls of each carton are simultaneously erected and set up.

8. A machine for handling cartons having their body portions collapsed with the side walls thereof folded over the end walls and the lids of the cartons overlying the same comprising a conveyor for advancing the cartons separately along a predetermined path, means associated with the conveyor for turning back the lids of the cartons to expose the body portions thereof, a hook pivotally mounted above said conveyor, means for releasing said hook for hooking engagement with the end wall at the trailing end of each carton during its travel therewith for raising the same and for subsequently holding said hook in a raised position, a rotatable finger adjacent said hook and above said conveyor, and means for continuously rotating said finger in timed relation with the operation of said hook and the advancement of said cartons to engage and raise the end wall at the leading end of each carton during its travel therewith whereby the end and side walls of each carton are simultaneously erected and set up.

9. A machine for handling cartons having their body portions collapsed with the side walls thereof folded over the end walls and the lids of the cartons overlying the same comprising a conveyor for advancing the cartons in a continuous flow along a predetermined path, means associated with the conveyor for turning back the lids of the cartons to expose the body portions thereof, a hook pivotally mounted above said conveyor, means for releasing said hook for hooking engagement with the end wall at the trailing end of each carton during its travel therewith for raising the same and for subsequently holding said hook in a raised position, a rotatable finger adjacent said hook and above said conveyor, means for continuously rotating said finger in timed relation with the advancement of said cartons to engage and raise the end wall at the leading end of each carton during its travel therewith whereby the end and side walls of each carton are simultaneously erected and set up, and means associated with the conveyor for preventing tilting of the cartons during engagement of said hook and finger therewith.

10. A machine for handling collapsed cartons having their lids overlying their body portions comprising a conveyor for advancing the cartons along a predetermined path, means associated with the conveyor for elevating and turning back the lids of the cartons to expose the body portions of the cartons, means cooperating with said conveyor for opening up the body portions of the cartons, and means associated with the conveyor at each side thereof for preventing tilting of the cartons during the body opening operation.

11. A machine for handling cartons having their body portions collapsed and their lids overlying the same comprising a conveyor for advancing the cartons along a predetermined path, means associated with the conveyor for turning back the lids of the cartons to expose the body portions of the cartons, carton opening fingers adjacent the path of travel of the cartons for entering the exposed body portion of the cartons and for spreading the end walls thereof to thereby open up the body portion of the cartons, and a hold down plate associated with the conveyor and disposed above the path of travel of the cartons adjacent the carton opening fingers for preventing tilting of the cartons during the opening of the body portions thereof, said hold down plate being provided with an elongated opening for permitting

operation of the carton body opening fingers therethrough.

12. A machine for handling cartons comprising a magazine for holding a stack of cartons having their body portions collapsed and their lids overlying the same, a conveyor for removing the collapsed cartons separately from the magazine and for advancing them in spaced relation in a file along a predetermined path, hold down guides associated with the conveyor for engaging the body portions of the cartons and for maintaining them in collapsed condition on said conveyor, means associated with the conveyor for turning back the lids of the cartons while the body portions of the cartons are held in collapsed condition by said hold down guides, and an oscillatable finger disposed above the path of travel of the cartons adapted to enter between the walls of the collapsed body portions of the cartons and to engage the trailing wall thereof and to raise the same during advancement of the cartons therewith, and a rotatable finger above the path of travel of the cartons adapted to enter between the walls of the collapsed body portions of the cartons and to engage and raise the leading wall thereof whereby the trailing and leading walls of the cartons are spread apart and the body portions of the cartons are opened up for subsequent filling thereof.

13. A machine for handling cartons having their body portions collapsed and their lids overlying the same comprising a magazine for holding a stack of collapsed cartons with their bottoms positioned downwardly, a conveyor for removing the cartons separately from the magazine and for advancing them bottom down in spaced relation along a predetermined path, hold down guides associated with the conveyor for engaging the body portion of the cartons and for maintaining them in collapsed condition on said conveyor, means intermediate said magazine and hold down guides for holding the body portions in collapsed condition during the discharge of the cartons from the magazine and prior and incident to engagement of the cartons by said hold down guides, means for turning back the lids of the cartons while the body portion of the cartons are held in collapsed condition by said hold down guides, a movable finger disposed above the path of travel of the cartons adapted to enter the collapsed body portions of the cartons to engage the trailing wall thereof and to raise the same during advancement of the cartons therewith, a rotatable finger above the path of travel of the cartons adapted to enter between the collapsed body portions of the cartons to engage the leading wall thereof and to raise the same whereby the walls of the cartons are spread apart and the body portions are opened for subsequent filling thereof, and means for controlling the operation of said fingers in accordance with the advancement of the cartons by said conveyor.

14. A machine for handling cartons having their body portions collapsed and their lids overlying the same comprising a magazine adapted to hold a stack of collapsed cartons with their bottoms presented downwardly, a conveyor for advancing the cartons bottoms down in a single file and in spaced relation from said magazine along a predetermined path, hold down guides associated with the conveyor for engaging the body portions of the cartons and for maintaining them in collapsed condition on said conveyor, means for turning back the lids of the cartons while the body portions of the cartons are held 75 in collapsed condition by said hold down guides,

an oscillatable finger disposed above the path of travel of the cartons and adapted to enter the collapsed body portions of the cartons to engage the trailing wall thereof and to raise the same during advancement of the cartons therepast, a rotatable finger above the path of travel of the cartons adapted to enter between the collapsed body portions of the cartons to engage the leading wall thereof and to raise the same whereby the walls of the cartons are spread apart and the body portions are opened up for subsequent filling thereof, a hold down plate disposed above the path of travel of the cartons intermediate said conveyor and carton opening fingers for maintaining the cartons in proper position on said conveyor during the carton body opening operation, said hold down plate having an elongated opening for permitting operation of the carton body opening fingers therethrough, means for continuously rotating said rotatable finger in timed relation with the advancement of the cartons by said conveyor, and means for controlling the operation of the movable finger in accordance with the advancement of the cartons by said conveyor.

15. In a carton handling machine a conveyor for advancing cartons having their body portions collapsed along a predetermined path, an oscillatable finger associated with said conveyor for engaging and raising one wall of the cartons during their travel therepast, a rotatable finger associated with said conveyor for engaging and raising another wall of said cartons, means for operating said fingers, and means associated with the conveyor for preventing tilting of the cartons 35 during the raising of the walls thereof.

16. In a carton handling machine a conveyor for advancing cartons having their body portions collapsed along a predetermined path, a rotatable carton body opening finger adjacent said path, 40 a movable carton body opening finger adjacent said path, means for continuously rotating said rotatable finger in timed relation with the advancement of the cartons by said conveyor, and means for raising and lowering said movable 45 finger into and out of engagement with the body portions of said cartons, said fingers being so disposed relative to each other and to said conveyor

as to engage and raise opposing walls of the body portion of each carton advancing therepast.

17. In a carton handling machine a conveyor for advancing cartons having their body portions collapsed separately along a predetermined path, a rotatable carton body opening finger adjacent said path, a movable carton body opening finger adjacent said path, means for continuously rotating said rotatable finger into and out of engagement with the body portion of each carton in timed relation with the advancement of the cartons along said path, a rotatable cam operatively associated with said movable finger, and means for operating said cam to release said movable finger for engagement with the body portion of each carton for subsequently holding said movable finger in a raised position out of the path of the cartons during a predetermined interval in the advancement of the same, said movable and rotatable fingers being so disposed adjacent each other as to simultaneously act upon the body portion of each carton advancing therepast to thereby erect the same.

CHARLES E. KERR.
ROSCOE ELSHEIMER.
